UNITED STATES PATENT OFFICE

2,445,848

MACHINE FOR PRESSING SOLES ON SHOES

Sidney J. Finn, Beverly, Mass., assignor to United Shoe Machinery Corporation, Flemington, N. J., a corporation of New Jersey

Application September 29, 1944, Serial No. 556,391

181 Claims. (Cl. 12—37)

1

This invention relates to machines for applying pressure to shoe bottoms and particularly to machines for use in the operation of permanently cement-attaching soles to shoes. The illustrated machine comprises a carrier rotatable about a vertical axis and a plurality of pads on the carrier to be presented in turn at an operating station by rotation of the carrier and is similar in some respects to the machine disclosed in United States Letters Patent No. 2,047,185, granted July 14, 1936, on application of Milton H. Ballard et al. It embodies also some of the features disclosed in United States Letters Patent No. 2,301,205, granted November 10, 1942, on my application, and No. 2,319,274, granted May 18, 1943, upon application of F. E. Stratton.

Objects of the invention are to provide a machine for this work which will be more compact, more effective and more nearly automatic than prior machines without, however, sacrificing any of their advantages.

Another object of the invention is to provide a form and means, such as gages, controlled thereby for accurately locating a sole of any size, either right or left, in predetermined position on the pad and for locating a shoe on the sole so positioned.

A further object of the invention is to control and operate various mechanisms of the machine by means of fluid pressure.

The illustrated machine is provided with eight pad boxes for four pairs of shoes, adjacent pad boxes being adapted one for a right shoe and the other for a left shoe. The pad boxes are arranged with the longitudinal axes of their foreparts in planes extending radially of the axis of the carrier or turret, the said axes being inclined upwardly and inwardly of the turret at an angle of approximately 45° to the horizontal. This construction permits a compact arrangement of the boxes and enables a single set of forepart gages to be arranged for movement into and out of position over the fixed forepart of the pad at the operating station in a direction parallel to the direction of the longitudinal axis of the forepart of the pad box at that station. The use of a single set of gages for cooperation with each of the eight pad boxes in turn instead of a set of gages for each pad box results in great economy of parts and more uniform operation of the machine. Each of the pad boxes comprises, besides the fixed forepart, adjustable shank and heel sections similar to those disclosed in my patent above mentioned, the pad boxes being thus adjustable to cause the pads to fit the contour of any shoe bottom.

2

The forepart gages comprise toe gages which engage the edge face of the sole at points on opposite sides thereof near the end of the toe and ball gages which engage the edge face of the sole substantially at the ends of the ball line. Since the ball line of the sole is oppositely inclined to the longitudinal median line in right and left soles, automatic means is provided for alternately shifting the ball gages, one up and the other down, longitudinally of the pad to locate them at the ends of the ball line first for the sole of the shoe for one foot and then for the sole of the shoe for the other foot, the pad boxes being arranged in pairs as above stated. The forepart gages when brought over the pad are initially located to receive the largest sole of the series of sizes being operated upon, and movement of the gages toward the sole is controlled by a form which has locating surfaces corresponding to the size and shape of any sole of a series of sole sizes for which the form is designed.

The form is mounted for movement perpendicular to the plane in which the gages move and is engaged by members representing the toe gages and the ball gages. By movement of the form, corresponding movements are imparted to these members which are connected to the gages. The form is duplex, one part controlling the gages for one shoe of a pair and the other part being reversely arranged and operated in a reverse direction to control the gages for the other shoe of the pair. While the gages are fully open, a sole is placed on the pad in engagement with the sole toe gage and the form is then moved to allow the toe gage to move longitudinally of the pad with the sole, and the ball gages to move laterally of the sole until they engage its edge face.

The heel end or breast line gages are arranged to swing in open position about a horizontal axis into and out of position over the heel end of the pad. Their axis is mounted on a carrier which is moved vertically toward and away from the rear end of the pad box at the operating station. When the carrier is raised the gages are swung about their axis into a position over the pad, the gages being then separated and hence in their inoperative positions. The gages are moved toward each other equally and oppositely to engage the sole, that is, to their operative positions, and are returned to their inoperative positions by operator-controlled fluid-pressure-operated mechanism which at times is automatically controlled to return the gages to inoperative position. The heightwise movement of the carrier may be varied

in accordance with the heightwise adjustment of the heel section of the pad box.

Shoe gages are provided on the sole toe gages for locating the forepart of the shoe, and other shoe gages are associated with the breast line sole gages for locating the rear end of the shoe relatively to the located sole. The shoe gages for the rear end of the shoe have surfaces that are inwardly and downwardly directed with respect to the sole and engage the shoe in the vicinity of the breast line to direct it into central position with respect to the sole.

Fluid-pressure-operated means under manual control are provided for moving the forepart gages into and out of operative position over the pad box, and provision is made for automatic operation of the gages at the proper times in the cycle of operations of the machine. Operator-controlled fluid-pressure-operated means is provided for moving the form, its direction of movement being determined automatically. The ball gages are moved oppositely to engage the sole by fluid-pressure-operated mechanism, the amount of their movement being determined by the position of the form.

The pad has a lower inflatable portion and an upper portion of solid resilient material such as rubber of substantial thickness. Between the resilient part and the inflatable part a mask plate is located, and means controlled by the form is provided for automatically varying the position of the mask plate longitudinally of the shoe in accordance with the size of the shoe. Provision is also made for varying the position to which the mask plate is automatically moved to accommodate shoes of different styles.

The mechanism for applying pressure to the shoe comprises two bails arranged to swing longitudinally of the pad box, one bail carrying a laterally movable abutment to engage the last and the other an abutment to engage the forepart of the shoe. The bails are initially swung inwardly of the turret. When the bail carrying the heel abutment is swung over the last, the toe abutment also moves over the forepart of the shoe and its position longitudinally is automatically determined in accordance with the size of the shoe. Provision is also made for varying the position automatically assumed by the toe abutment to accommodate shoes of different styles.

Fluid-pressure-operated mechanism under manual control is provided to force the abutments toward the shoe and the shoe toward the pad, and the pressure thus applied is maintained by spring-actuated wedges which act automatically to operate pawls engaging toothed struts to lock the abutments down in pressure-applying position and to take up the space between the teeth of the struts to maintain all the pressure applied.

During the application of pressure to the shoe, the gages, having now served their purpose, are all caused to be withdrawn to their inoperative positions. After a predetermined pressure has been applied to the shoe, the wedges are allowed to be drawn in by their springs to hold all the pressure so applied and valves are operated to permit inflation of the pad. After the wedges have operated, pressure builds up to a predetermined amount and then operates an exhaust valve to release the pressure in the fluid-pressure-operated means for depressing the abutments which are now held in pressure-applying position by the wedges.

Means under manual control, for example a

treadle, is now operated to cause inflation of the pad, and when the pad pressure reaches a predetermined amount it opens a valve to a line which is open only if the forepart gages have returned to their inoperative positions and if the fluid-pressure-operated elements which applied pressure to the shoe and raised the carrier for the heel gages have returned to inoperative position. This line leads to the indexing mechanism, and pressure therein withdraws the indexing pin and opens a valve in the exhaust line of a fluid pressure motor for turning the turret which now rotates to bring the next pad to the operating station.

The exhaust from the motor passes to a timing valve which is thereby set to prevent indexing of the turret again until a predetermined time has elapsed, thus insuring that the operation of the machine will not be speeded up to such an extent that the shoes will be relieved of pressure before a proper cement bond has been effected.

When a shoe under pressure passes from the operating station to the next station, the inflating pressure therein is maintained until that shoe arrives again at the operating station where the inflating pressure is exhausted and pressure on the shoe is momentarily applied to control spring means by which the pressure-applying means is raised and to permit easy retraction of the wedges which are then withdrawn, pressure on the shoe released and the gages moved again into operative position over the pad for locating the next sole on the shoe.

If the bails at the operating station remain in their inoperative positions, that is, if no further shoes are being treated and it is desired to remove those in the machine, the turret may be indexed by operating the manually operated means which normally controls the inflation of the pad. Under these circumstances substantial depression of the abutments is prevented, the inflating valve is not opened and the fluid pressure acts only to withdraw the indexing pin and cause operation of the indexing motor.

These and other features of the invention will appear more fully from the following description when read in connection with the accompanying drawings and will be pointed out in the appended claims.

50 In the drawings,

Fig. 15 is a view showing the gage mechanism with the gages in advanced position over the forepart of the pad, the view being taken perpendicular to the plane in which the gages operate;

Fig. 15a is a detail sectional view of the pad box taken on the line XVa—XVa of Fig. 15;

Fig. 16 is a perspective view of the form and form toe gage;

Fig. 17 is a view, mostly in section, of the pressure-operated mechanism for raising the carrier on which the rear or breast line gages are mounted;

Fig. 18 is an elevation, partly in section, of mechanism for moving the form up or down and the manually operated means for controlling its movement;

Fig. 19 is an elevation taken from the left of Fig. 18;

Fig. 20 is a detail of the ball line sole gages;

Fig. 21 is a view of the sole toe gage and its connections;

Fig. 22 is a side elevation of parts shown in Fig. 21;

Fig. 23 is an enlarged view, partly broken away, of parts shown in Fig. 21;

Fig. 24 is a front elevation, partly in section, of parts shown in Fig. 23;

Fig. 25 is an elevation of the sole-engaging face of a portion of the toe gage taken from the left side of Fig. 23;

Fig. 26 is a perspective detail of parts shown in Figs. 23, 24 and 25;

Fig. 27 is a side elevation of the breast-line gages and their operating mechanism;

Fig. 28 is a view, partly in section, of parts shown in Fig. 27;

Fig. 29 is an elevation, partly in section, of the rear end or breast line gages showing the mechanism by which their movements toward and from each other are controlled;

Fig. 30 is a sectional view on the line XXX—XXX of Fig. 29;

Fig. 31 is a side elevation of the mechanism for applying pressure to the shoe;

Fig. 32 is a view of the heel abutment shown in Fig. 31 looking in the direction of the arrow;

Fig. 33 is a side elevation, partly in section, of the parts shown in Figs. 31 and 32;

Fig. 34 is an elevation, partly in section, taken from the right-hand side of the mechanism for applying pressure to the shoe showing also the motor for retracting the wedges;

Fig. 35 is a view, partly in section, taken along the line XXV—XXV of Fig. 34;

Fig. 36 is a fragmentary front elevation, partly in section, of parts shown in Fig. 35;

Fig. 37 is a sectional view taken on the line XXXVII—XXXVII of Fig. 35;

Fig. 38 is a fragmentary view similar to Fig. 37 showing the parts in a different position;

Fig. 39 is a sectional view of the indexing pin, the fluid-pressure-operated means for withdrawing it and the timing mechanism by which a second retraction of the pin is prevented for a predetermined time;

Fig. 40 is a top view of parts shown in Fig. 39;

Fig. 41 is a side view of the parts shown in Fig. 40, a fragment of the casing being shown in section;

Fig. 42 is a fragmentary sectional view on the line XLII—XLII of Fig. 41;

Fig. 43 is a diagrammatic view showing the operating parts of the machine after the turret has just been indexed and before the gages have moved to operative position on the pad;

Fig. 44 is a view similar to Fig. 43 showing the positions of the parts after the pressure-applying treadle has been operated;

Fig. 45 is a view similar to Fig. 43 showing the positions of the parts after a pad has been inflated and the indexing pin is about to be withdrawn; and

Fig. 46 is an enlarged view of a portion of Fig. 43.

25 The illustrated machine (Figs. 1, 2 and 3) comprises an octagonal base portion 50 formed to provide a reservoir or sump to receive a supply of pressure fluid such as oil from which pumps P—1, P—2 driven by an electric motor M (Fig. 3)

30 supply fluid under pressure to operate various instrumentalities of the machine. At each of the corners of the base is an upright 52 (Fig. 1), and connecting the upper ends of the uprights are cross portions 54, the rectangular openings thus formed being normally closed by plates 56, the plates being removed in Fig. 2 to show the mechanism enclosed in the base.

From the center of the base portion rises a hollow post or column 58 (Fig. 4) upon which is rotatably mounted a sleeve 60. On the lower end of the sleeve is a large gear 62 by which it may be rotated, and on the upper end of the sleeve is secured a hollow frame 64 to which are secured by screws 66 eight brackets 68 which carry the pads and pressure-applying devices.

The gear 62 at the bottom of the sleeve 68 meshes with a pinion 70 (Fig. 3) driven from a bevel gear 72 through a mechanism similar to that disclosed in United States Letters Patent No.

50 2,314,278, granted March 16, 1943, in the name of L. E. James. The ratio of the gear 62 to the pinion 70 is 1 to 8, and one rotation of the gear 72 at uniform speed will impart, through the James mechanism, to the pinion 70 first a slow speed, then an acceleration and then a deceleration. Thus, the turret (comprising the sleeve 68 and the eight pad boxes and pressure-applying devices carried thereby), when being indexed one-eighth of a revolution, is started slowly, then

55 speeded up and then slowed down. The gear 72 is driven by a rotary fluid-pressure motor 74 the shaft of which carries a beveled pinion 76 meshing with the gear 72. This motor may be of the type disclosed in United States Letters Patent No. 2,300,009, granted October 27, 1942, upon application of E. L. Rose.

The eight pad boxes are all alike except for right and left characteristics and hence only one will be described in detail. Each bracket 68 comprises vertical side walls 78, 80 and an intermediate portion 82 (Figs. 31, 34, 35 and 36) the outer surface of which is inclined at an angle of approximately 45° to the horizontal and supports a forepart portion 84 of the pad box. A shank portion 86 (Fig. 34) of the pad box is pivoted at 88

to the forepart portion, and a heel portion 90 thereof is pivoted at 92 to the shank portion. On the lower side of the heel portion 90 are ears 94, 96 (Fig. 36) to which links 98, 98 are pivoted by pins 98. The lower ends of the links 98 surround trunnions 100, 100 on a sleeve 102, and in the center of each trunnion is a pin 104 the outer end of which is secured in one branch of a U-shaped lever 106. The ends of the lever are pivoted by pins 108, one to the side wall 78 and the other to the side wall 80 of the bracket 68 (Fig. 35). The closed end of the U-shaped lever 106 (Fig. 34) carries a toothed segment 110 which is engaged by one of a pair of differential pawls 112, 114 (Fig. 31) mounted on a shaft 116 journaled in ears formed on a cross member 118 connecting the side walls 78, 80 of the bracket. The shaft 116 is bent to form a handle 120 and the pawl 112 is fixed by a setscrew 122 (Fig. 34) to the shaft. This pawl 112 carries a pin 124 which engages a slot or lug in the other pawl 114 and the pawls are urged toward the segment 110 by compression springs 126 located between the bar 118 and their lower ends. By turning the handle 120, first the pawl 112 and then the pawl 114 may be moved away from the segment 110 to release it, and then the lever 106 may be raised or lowered about its pivots 108 to adjust the heel part 90 and the rear end of the shank part 86 of the pad box up and down relatively to the pivot 88 which connects the shank part to the fixed forepart portion 84 and thus change the angular relation of the shank part to the forepart to change the contour of the pad and pad box to accommodate shoes that are to have heels of different heights. The heel portion 90 of the pad box is further supported by a pair of five-sided cams 128, 130 (Figs. 34 and 35) fixed to a shaft 132 which is rotatably mounted in upstanding ears 134 one on each of the branches of the U-shaped lever 106. The cams 128, 130 together support the rear end of the pad box and each side of each cam is at a different distance from the shaft 132 so that, by rotating the shaft by means of a knob 136, the position of the portion 90 of the pad box about the pivot 92 may be varied. To insure that the cams will not be accidentally rotated and to hold down the rear end of the portion 90, the shaft 132 is mounted for movement longitudinally and the cam 130 is provided with a series of slots 138 parallel to its faces each of which, by longitudinal movement of the shaft 132, may be engaged with or disengaged from an angular plate 140 (Fig. 34) secured to the part 90. A compression spring 142 (Fig. 35) located between the cam 128 and one of the ears 134 urges the shaft 132 longitudinally in a direction to hold the cam 130 in engagement with the plate 140 from which it may be disengaged by pushing on the knob 136 which may then be turned to locate other surfaces of the cams 128, 130 in position to support the part 90 at different inclinations.

A pad 144 which is supported by the parts 84, 86 and 90 of the pad box may comprise (Fig. 15a) a lower inflatable portion 146 and an upper portion 148 of yielding material such as rubber which preferably is of considerable thickness, the construction being substantially as disclosed in United States Letters Patent No. 2,356,756, granted August 29, 1944, upon an application of mine. Between the inflatable layer and the rubber layer is a mask plate 150 which, as will later be explained, is moved longitudinally of the pad in accordance with the size of the sole which is being attached to the shoe to control the amount

of wrap given to the sole when the shoe and sole are pressed together. On the forepart of the pad (Fig. 9) is a plate 152 having a U-shaped opening 154 large enough to receive the largest sole. In locating the sole on the pad, a sole form or templet designated generally by the numeral 156 is used the construction of which is based on sole patterns for the largest and smallest soles of a run of sizes. In Fig. 16 a plate 158 represents a sole pattern for the largest right sole of a run of sizes and a plate 160 the smallest sole pattern. These plates or sole patterns are arranged in planes parallel to each other and spaced apart a convenient distance, for example about an inch. The ball lines are arranged one over the other, the distance between the ends of the ball lines at each side being made the same. The space between the plates could be completely filled to make a form representing the size and shape of the foreparts of all the soles of a run of sizes. Since, however, the form is employed for sole-locating purposes, it is necessary to use only a few salient points on the form, for example four. Accordingly, the plates are joined by struts, a strut 162 connecting the end of the ball line of the large plate 158 to the end of the ball line of the small plate 160. Conveniently the struts may be welded to the plates and the outer edge 163 ground to form a straight surface extending from one plate to the other, the position of the end of the ball line of any intermediate size of sole being represented by some point on this surface. Another strut 164 is fitted in a similar manner between the ends of the ball lines of the plates at the opposite side. At the toe ends the plates are joined by struts 166, 168 arranged so as to be squarely engaged by a form toe gage movable laterally and longitudinally of the pad, as will be hereinafter explained. The form for the left soles is made in a similar manner and the corresponding parts thereof are designated by the same numbers primed. The two forms, one for the right soles and the other for the left soles, are placed with the large plates 158, 158' next to each other with a spacing plate 170 between them, and, by means of the last for which the sole patterns were made, the right and left swing required for the forepart of the last with respect to its rear part is determined, the right form being swung to the left and the left form to the right. The swing of the forepart of the last with respect to its rear part is usually about 7° so that the angle between the longitudinal median line of one form with respect to the longitudinal median line of the other will be twice that or 14°. The two forms are secured together at the angle so determined by rivets 171 to make a single duplex form indicated as a whole by the reference numeral 156. It will be observed that the form roughly resembles a pair of truncated cones arranged with their bases next each other, parts of the cones which serve no useful purpose being omitted.

The form is mounted in the machine as best shown in Figs. 6 and 13. A stationary head frame 172 is secured to the top of the column 58, and in a hole 174 (Fig. 13) in the head frame is mounted a shaft 176 with its longitudinal axis extending in a direction perpendicular to the plane of the forepart of the pad. On the shaft 176 is a form-supporting plate 178 in which are two slots 180, 182 which are engaged by downwardly projecting pins 184, 184 on the plate 160' of a size to fit the slots. The form plates 158, 160, 158' and 160' are provided with aligned openings 186 (Fig. 16) to fit the shaft 176 and, when the form is slipped

over the shaft and rotated until the pins 184 in the plate 168 engage the slots 180, 182, it is held against rotation. To hold the form against movement away from the supporting plate 178, a spring-pressed latch 188 (Fig. 13) is pivoted to the supporting plate and engages the plate 158 of the form. To prevent any rotation of the supporting plate 178, the slot 182 is extended to engage a guide 190 fixed to the frame 172 with its lateral surfaces perpendicular to the plane of the forepart of the pad and engaging the sides of the slot 182.

The supporting plate 178 is moved along the shaft 176 to raise and lower the form by a lever 192 fulcrumed at 194 to a bracket 196 secured to the head frame 172, the forward end of the lever being bifurcated and each arm connected by a link 198 to the supporting plate 178. The rear arm of the lever 192 (Fig. 6) has a screw 200 which is threaded into a lug on an arm 202 pivoted at 194. The rear end of the arm is pivotally connected to an operating rod 204 which extends down through the center of the turret post 50. The arms 192, 202 constitute an angle lever the angularity of the arms of which may be varied by turning the screw 200 and the rocking of which by the longitudinal movement of the rod 204 will move the form up and down.

The rod 204 extends to the base of the machine (Fig. 18) where it is connected by a readily removable pin 206 to the bifurcated end of an arm 208 of a three-armed lever fulcrumed at 210. One of the bifurcations of the arm 208 is slotted to receive a leaf spring 212 which engages a notch in the pin 206. Another arm 214 of the three-armed lever has a roll 216 engaging a wedge cam 218 which has two diverging surfaces 220, 222 between which at their forward ends is a recess or pocket 224 slightly larger heightwise than the roll 216. A third arm 226 of the three-armed lever is engaged on one side by a motor designated by the symbol M-1 comprising a piston 228 in a cylinder 230 so that when pressure fluid is supplied to the left end of the cylinder through a pipe 232 the piston 228 will move the arm 226 in a direction to hold the roll 216 against the upper surface of the pocket 224 of the wedge cam. This insures that the rod 204 will be drawn down and the form pushed up a distance equal to the thickness of the spacing plate 176 to a position such that the plate 158 of the left-hand form will be in the plane of movement of the form gages, one of these, namely a form toe gage 234, being shown in Fig. 16 as engaging, with its diverging branches 235, 236, the edge of the plate 158.

When the cam 218 is moved to the left (Fig. 18), the roll will follow the surface 220 and the form will be raised to allow the gage 234 to advance to the extent desired for the left sole being located.

When a right sole is being positioned on the next pad, the pressure fluid is automatically shifted, as will be explained, to a pipe 238 connected to the opposite end of the cylinder 230 and causes a piston 240 to press the arm 226 in a direction to hold the roll 216 at first against the lower side of the pocket 224 to locate the plate 158 of the form opposite the form toe gage 234 so that, as the wedge cam 218 is moved in the same direction as before, the roll 216 will follow the cam face 222 of the cam and control the upward movement of the rod 204 and hence downward movement of the form relatively to the form toe gage 234.

The wedge cam 218 has gib 242 sliding in ways 244 to guide its movement as described and is moved manually by a treadle A. A horizontal lever 246 (Fig. 19) is fulcrumed between its ends at 248 and has on one arm a roll 250 engaging a transverse slot in the cam 218, the other end of the lever being connected by a rod 252 (Fig. 4) to one arm 254 of an angle lever having a fixed fulcrum at 256. The other arm 258 of the angle lever is loosely connected to a slide 260 guided in vertical ways on the base 50 and connected by a link 262 to a treadle lever 264 fulcrumed at 266 to the base and held raised by a spring 268 connected at one end to a bracket on the base 50 and at the other end to the lever 264 forwardly of its fulcrum. Depression of the treadle A on the lever 264 will move the wedge cam forwardly to permit movement of the form either by the piston 228 or by the piston 240, depending on which is being supplied with pressure at the time. Rearward movement of the wedge cam 218 (Fig. 18) in response to the action of the spring 268 is limited by a stop screw 270 threaded through a lug 272 on the cam 218 and arranged to engage the adjacent end of the cylinder 230, and forward movement of the wedge cam is adjustably limited by a stop screw 274 located to be engaged by the stop screw 270.

The form toe gage 234, a sole toe gage 214 and a shoe toe gage 275 are mounted on a toe gage carrier (Figs. 9 and 11) which comprises a lower body portion 276 (by which numeral the carriage will be generally designated), end walls 278, 280 and a top plate 282 secured to the end walls by screws 284 (Fig. 15). The form toe gage 234 is guided for movement longitudinally of the pad 144 by ribs 286 (Fig. 11) formed on the upper face of the portion 276 and has a slot through which a screw 288 extends (Fig. 6), the screw being threaded into the portion 276. For convenience in loosening the screw, its head is extended upwardly and provided with a laterally extending handle 290. A rod 292 (Fig. 6) is journaled in the body portion 276 and carries an eccentric 294 which engages a transverse slot in the gage 234. The rod has a flange 296 resting on the gage and a knurled head 298 by which the eccentric may be turned to adjust the gage toward and from the form when the screw 288 is loosened by turning the handle 290. The head 298 passes through an opening in the plate 282 and has a circumferential groove engaging a retaining plate 299 secured to the plate 282 to hold the rod 292 against upward movement. By removing the retaining plate the rod 292 may be pulled up to release the eccentric from the gage 234 which may be removed by turning out the screw 288.

On the lower side of the body portion 276 of the toe gage carrier are two recesses 300, 302 widely spaced laterally from each other (Fig. 11), the recess 300 receiving a cam bar 304 and the recess 302 receiving a cam bar 306. The reason for referring to these as cam bars will later appear. The depth of the recesses is equal to the thickness of the cam bars but their extent widthwise of the cam bars is much greater than the width of the bars so the carriage 276 can move laterally as well as lengthwise thereon. Beneath each cam bar is a plate 308 secured to the carriage 276 by screws 310, the plates holding the carriage from heightwise movement with respect to the cam bars. The cam bars 304, 306 (Fig. 9) are mounted parallel to each other in guides on the head frame 172 for movement lengthwise in a plane parallel to the forepart of the pad, the

cam bar 304 having guides 312, 314 on one side of the head of the machine and the cam bar 306 having similar guides 316, 318 on the other side. Secured to the under side of each plate 306 (Fig. 11) is a rack 320 and each rack is engaged by a toothed segment 322, the toothed faces of the segments being wide enough to permit the desired lateral movement of the carriage 276. Each segment 322 has an arm 324 which is pinned to a shaft 326 journaled in the head frame 172. On the shaft 326 (Fig. 13) is an arm 328 carrying a roll which is engaged by a plunger 330 working in a cylinder 332 constituting a motor M-2. The lower end of the cylinder is supplied with pressure fluid by a pipe 334, and action of the plunger will swing the segment arms 324 to move the toe gage carriage 276 toward and from the form 156.

The end walls 278, 280 of the gage carriage 276 have ears 336 at their forward ends (Fig. 9) which engage trunnions 338 formed on the cross-bar of a T-shaped member 340 which can therefore swing about a horizontal axis, the member 340 being held in either its raised or its lowered position about that axis by a leaf spring 342 which is engaged by a projection 344 secured to the right-hand trunnion 338. A gage support 346 is secured by screws 348 to the forward end of the member 340 and carries both the sole gage 274 and the shoe gage 275 which, as shown in Fig. 15, has diverging arms with an opening between them through which the end of the sole may be seen, the arms having surfaces 350, 352 (Fig. 9) substantially at right angles to each other for locating the toe end of the shoe. The gage support 346 (Fig. 22) is provided with a longitudinal guideway in which is a slide 354 which, at its front end, has a transverse groove 356 to receive a corresponding rib on the shoe toe gage 275 which is held to the slide by screws 358 (Fig. 21), the screw holes being elongated laterally to permit sidewise adjustment thereof relatively to the slide 354. A plate 360 is secured by a screw 362 and dowel pins to the slide 354 and carries a pin 364 which engages an oblique slot 366 in a block 368 mounted to slide transversely of the support 346 in ways 370. The block 368 has a threaded hole to receive a thumb screw 372 which is held from longitudinal movement by a plate 374 having a notch to engage a groove in the screw 372 and secured to the support 346 by screws 376. By turning the thumb screw 372 the slide 354 and the shoe toe gage 275 may be moved longitudinally of the shoe relatively to the sole gage 274 to vary the amount of projection of the sole relatively to the shoe.

The sole toe gage 274, which may, as shown in Figs. 21 and 22, be integral with the support 346, has two branches at right angles to each other with an opening between them, the branches having outer surfaces 380, 382 which are parallel to the surfaces 350, 352 of the shoe toe gage 275. Three thin plates 388, 390, 392 (Fig. 24) are secured by screws 394 to each of the outer faces 380, 382. The two upper plates 388, 390 are bent at right angles and the lower plate 392 at an obtuse angle, thus providing a space between the plates 388, 392. In the space thus provided is a series of sole-engaging members formed of wire in the shape of loops as shown in Fig. 26. A portion 398 of the wire engages the edge of the sole and portions 400, 402 are seated in sockets or depressions 404, 406 formed in the upper side of the middle plate 390 (Fig. 23) which also has a pocket 408 to receive an end portion 410 of the wire which is bent to one side with respect to a

straight portion 412 thereof. It will be seen that the portion 410 is confined between the plates 388, 390, the inner edge of the plate 388 being bent over the edge of the plate 390 at 414 (Fig. 24) to hold the plates together. The portions 400, 402, seated in the sockets 404, 406, form a hinge about which the portions 388, 412 may be swung against the torsional stress developed in the wire by holding the lateral arm 410 from movement. The portion 398 is normally inclined at a considerable angle to the plate 392 (Fig. 25) so that when pressure is applied to the plate 388 with the plate 392 supported on the pad, the portions 388, 412 will slip sidewise and allow the inner portions of the plates 388, 392 to approach each other. The plates all project somewhat beyond the sole-edge-engaging portion 398 of the wire members so that the lower face of the sole will rest on the projecting portion of the plate 392 and the projecting portions of the plates 388, 390 will lie over the sole and will be engaged by the shoe when its toe end is in contact with the surfaces 350, 352 of the shoe gage. The projecting portions of the plates will therefore initially sustain the shoe out of contact with the sole but, when pressure is applied to the plates by the shoe, the wire members which locate the sole will swing on their hinges and allow heightwise collapsing of the gage by movement of the plate 390 toward the plate 392. When pressure is removed, the resiliency of the plates and the torsional stress produced in the wires by the arms 410 will restore the parts to initial position.

In the normal retracted position of the toe gage carriage 276 the sole toe gage 274 (Fig. 9) rests by gravity on the rear portion of the cover plate 152 of the pad box and the form toe gage 234 is located rearwardly of the form and in a central position to which it is moved by engagement of inclined surfaces 450, 452 on plates 454, 456 secured by screws 458 to the body portion 276 of the carriage with a roll 460 (Fig. 6) which is mounted on a forwardly and downwardly inclined stud 462 fixed at 464 to the head frame 172. When the carriage is retracted, it normally will have been shifted laterally so that one or the other of the surfaces 450, 452 of the plates 454 will engage the roll 460 and will shift the carriage to a central position and the roll will then enter a space between the plates 454, 456 just wide enough to receive the roll. When the carriage moves down, therefore, it will be in a central position, and when one of the prongs 235, 236 of the form toe gage 234 engages the form the carriage will shift laterally until the other prong engages the form and will then stop. Thus, the sole toe gage 274 and the shoe toe gage 275 will advance into operative position on the pad and will be shifted laterally of the pad to receive the toe of the largest right or left shoe, depending upon whether the right form 158 or the left form 158' is then in position for use.

Movement of the form 156 either up or down will then allow the gage 274 to push any sole smaller than the largest sole downwardly on the pad until the ball line gages, which are herein-after described, contact the sides of the sole, and thus the toe of any sole will be located upon the pad in the position determined by the form, the toe gages being held against retractive movement by continued fluid pressure in the motor M-2.

In Fig. 9 the ball-line sole gages 470, 472 are shown in retracted positions and in Fig. 15 are shown in their advanced positions. The gages

are advanced over the forepart of the pad, located in positions nearly opposite the ends of the ball line of the largest shoe and alternately shifted, the one up and the other down, to locate them directly opposite the ends of the ball line of the sole first, for example, for a left shoe and then for a right shoe as these are being laid on successive pads.

For this purpose the following mechanism is provided: The ball-line sole gage 470 (Fig. 20) is secured to an arm 474, shown on the right-hand side of Fig. 9, which is pivoted by a horizontal pin 476 to two widely separated ears 478 on a bracket 480 secured to a bar 482 mounted to slide longitudinally in guideways 484, 486, the guideways being separated a considerable distance lengthwise of the bar and mounted in a manner to be described. The arm can swing on the pin 476 and rest by gravity on the plate 162. The arm 474 carries a flattened pin 487 which engages the outer sides of a slot 488 in the lower end portion of the bar 482 to prevent lost motion in the ears 478.

The opposite ball-line sole gage 472 has an arm 489 (Fig. 6) similarly mounted on a bar 490 which has guideways 492, 493 similar to the guideways 484, 486. The bars 482 and 490 are slid longitudinally in their guideways to move the gages 470, 472 into operative position on the pad by a lever having a long arm 494 fulcrumed at 496 on the head frame 172 and having at its upper end a crosshead 498 (Fig. 9). At each end of the crosshead is an ear 500 formed on a pin 504 journaled in the crosshead and through each ear a rod 502 freely passes. Each rod is pivoted at 504 to a pair of ears, one pair being on the bar 482 and the other pair on the bar 490. The rods 502 have collars 506 between which and the ears 500 are compression springs 508 so that counterclockwise movement of the lever 494 (Fig. 6) will move both bars 482, 490 yielding downwardly through the springs 508 to carry the ball-line gages 470, 472 over the pad. The rods 502 have heads above the ears 500 so that the reverse movement of the lever 494 will positively retract the bars 482, 490 and the gages carried thereby.

A short arm 510 (Fig. 6) of the lever 494 carries a roll 512 which is engaged by a plunger 514 working in a cylinder 516, designated as motor M-3, to which fluid under pressure is supplied by a passage 518 extending up through the fixed column 58 and connected to a distributing head 520 from which a short pipe 522 leads to the bottom of the cylinder 516.

To retract the gages, a roll 524 (Fig. 6) on the lever arm 494 above its fulcrum 496 is engaged by a plunger 526 sliding in a cylinder 528 and constituting motor M-4. This motor is supplied with fluid under pressure to operate the plunger 526 by a pipe 530 which comes up through the column 58 and is connected to the bottom of the cylinder through a needle valve 532 and a ball valve 534, the needle valve serving to regulate the flow of fluid into the cylinder so that the gages will not be retracted too rapidly, and the ball valve retarding the exhaust of fluid from the cylinder so that the gages will not be carried down too quickly by the action of the motor M-3. The sole ball gage bar 482 has a projection 536 (Figs. 9 and 11) carrying a downwardly projecting pin 538 which, as the bar is moved to retract the gage 470, engages the top plate 282 of the toe gage carriage and retracts it also.

Form ball gage bars 540, 542 (Fig. 9) are arranged beneath the sole ball gage bars 482, 490

for movement toward and from each other in parallel relation. In Fig. 9 the left-hand form ball gage bar 542 is shown as having a slot 544 near its lower end and a slot 546 some distance from its upper end. In these slots are pins 550 which permit a limited longitudinal movement of the bar. The pin 550 at the lower end of the bar 540 (Fig. 14) has a washer and nut 552 on its lower end to support the bar 540 and extends up through widely spaced ears 554, 556 on a webbed arm 558 of an elbow lever having a fixed pivot pin 560 the lower end of which is seated in a lug 562 on the head frame 172 and the upper end in a similar lug 564 on the frame. On the upper end of the pin 550 is pivotally mounted the guideway 484 for the ball-line gage bar 482. In Fig. 13 is shown an exactly similar mounting of the upper guide 486 for the bar 482 on the pin 550 which is carried by a lever arm 566 similar to the arm 558 and having a fixed pivot at 568.

The upper and lower pins 550 of the left-hand bar 542 are mounted in the same way on arms 510, 512 which correspond respectively to the arms 566, 558. The arms 566, 558 can swing inwardly to permit the right-hand bar 540 to move parallel to its initial position until a form ball gage 574 projecting from the bar 540 engages the form and will carry the guideways 484, 486 and the bar 482 parallel to its original position to locate the ball-line sole gage 470 on the pad. The arms 510, 512 allow the left-hand bar 542 to move inwardly parallel to its initial position until a form ball gage 576 engages the opposite side of the form and causes the guideways 492, 493 of the bar 490, each pivoted on one of the left-hand pins 550 (Fig. 6), to move the ball-line sole gage 472 over the pad toward the gage 470.

The form ball gage bars 540, 542 are oppositely moved up or down, as permitted by the slots 544, 546, to locate the projections 574, 576 thereon in position to engage the struts 162, 164 if the upper form is in use or the struts 162', 164' if the lower form is in use, and the longitudinal movement of the sole ball gage bars 482, 490 is limited in accordance with the position assumed by the form ball gages or projections 574, 576.

Shifting of the form ball gage bars 540, 542 is effected as follows: When the lever 494 (Fig. 6) is moved clockwise to retract the ball gages, a surface on the rear face of the lever engages a roll 580 (Fig. 7) adjustably mounted on a plunger 582 arranged to slide through a casing 586 secured to the head frame 172. The plunger is bored lengthwise to receive a spring 588 and is slotted lengthwise to receive a pin 590 fixed in the casing, the spring 588 being located between the bottom of the bore and the pin so that the spring will move the plunger back when released by the lever 494. In the casing 586 is a fixed stub shaft 592 on which is loosely mounted a segmental member 594 connected to the plunger 582 by a link 596. Pivoted to the member 594 is a pawl 598 urged by a spring 600 to engage a ratchet wheel 602 to which is fixed a gear 604 loose on the shaft 592 and meshing with a pinion 606 which has an integral cylindrical hub 608 journaled in the casing 586 (Fig. 8). The hub has a reduced extension threaded to receive nuts 610, and a compression spring 612 is located on the stem between washers, one washer engaging one of the nuts and the other engaging the casing. Between the pinion 606 and the casing is a pair of friction washers 614 which are pressed together by the spring 612 to prevent overrunning of the pinion 606 when turned by the pawl 598.

On the top of the pinion is an eccentric pin 616 (Fig. 7) which engages a slot in one arm of a lever 618 fulcrumed at its middle point on the stub shaft 592. The slotted arm of the lever is connected by a link 620 to the bar 546 and the other arm is connected by a similar link to the bar 542 (Fig. 9). When the lever 618 is moved clockwise (Fig. 6) as far as it will go, the plunger 582 is moved far enough to cause the pawl 580 to impart to the gear 604 a partial rotation sufficient to turn the pinion 606 180°, that is, from the position shown in full lines in Fig. 7 to the position shown in dotted lines or vice versa. Thus, the bars 540, 542 are moved the one up and the other down as permitted by the slots 544, 546 to locate the form ball gages 574, 576 opposite the ends of the ball line of a right or left sole, as represented by the struts 162, 164 of the right form or the struts 160', 162' of the left form.

To similarly position the ball-line sole gages 470, 472, the bars 540, 542 are provided with upstanding abutments 624 (Figs. 9 and 13) which are positioned to be engaged by screws 626 (Fig. 4) threaded through lugs 628 on the upper ends of the ball gage bars 482, 490. When these bars are moved downwardly by the action of the plunger 516 the screw 626 of the bar 482 may first engage the abutments 624 on the bar 540, and the spring 508 through which that bar is moved will be compressed to permit the screw 626 on the bar 490 to engage its abutment 624 on the bar 542.

The sole toe gage 274 has now been moved over the pad and positioned by contact of the form toe gage 234 with the struts 160', 162', for example, of the form, and the ball-line sole gages 470, 472 have been moved over the pad and located longitudinally thereof in accordance with the positions of the form ball gages 574, 576. It is now only necessary to move these gages oppositely to engage the struts 160', 162' of the form and to correspondingly move the ball-sole gages 470, 472 toward each other to set these gages for the largest sole. This is effected by longitudinal movement of the cam bars 304, 306 toward the pad. The cam bar 304 (Fig. 9) has parallel grooves 628 which are inclined at about 30° to the longitudinal axis of the bar. Each groove is engaged by a pin 630 one in an arm 632 and the other in an arm 634. The arm 632 is fast to the arm 558 (Fig. 14) which is connected to the form ball gage bar 540, and the other arm 634 (Fig. 13) is fast to the arm 556 connected to the same gage bar. Therefore, when the cam bar 304 is moved longitudinally toward the pad, the bar 540 will be moved bodily to the left (Fig. 9) to cause the form ball gage 574 to engage the strut 160' of the form. The opposite cam bar 306 has parallel grooves 636 inclined at about 60° to the grooves 628. The lower groove 636 is engaged by a pin 638 on an arm 640 which is fast to the arm 572, and the upper groove is engaged by a pin 642 in an arm 644 fast to the arm 570. Downward movement of the bar 306 will therefore move the form gage bar 542 bodily parallel to its initial position to cause the form ball gage 576 to engage the strut 162'. Since, as above indicated, the guideways of the ball line sole gage bars 482, 490 are carried by the same arms as the form gage bars, they will be moved toward each other in parallel relation distances corresponding to the movement of the form ball-line gages 574, 576.

To move the cam bars 304, 306 in unison toward the pad, the shaft 496 on which the lever

494 is fulcrumed is extended through the frame 172 (Fig. 10) and has an arm 646 pinned to each end. Each arm is connected by a link 648 to one of the cam bars 304, 306. The shaft is rocked to move the cam bars down by a plunger 650 (Fig. 13) working in a cylinder 652 constituting a motor M-5. The closed end of the cylinder is supplied with fluid under pressure by a pipe 654 which leads to the distributing head 520 (Fig. 8).

The plunger 650 (Fig. 13) engages a roll on an arm 666 fixed to the shaft 496 and operates in a direction to turn the shaft clockwise in that figure and hence to move the cam bars 304, 306 toward the pad, thereby causing both the form ball gages 574, 576 and the sole ball gages 470, 472 to move equally and oppositely toward each other.

Reverse movement of the cam bars 304, 306 is effected by a plunger 662 (Fig. 13) working in a cylinder 664 designated as motor M-6. The plunger engages a roll on the end of an arm 666 fixed to the shaft 496 and is operated by pressure fluid supplied to the lower end of the cylinder 664 by a passage 670 connected to a pipe 672 which extends down through the center of the turret post parallel to the pipe 650 which supplies the cylinder 652. These pipes 650, 672 are at the base of the turret post connected to a single line 674 (Fig. 3). The plunger acts to turn the shaft 496 counterclockwise to retract the cam bars. Entrance of pressure fluid into the cylinder 664 is controlled by a needle valve 676 and exhaust of fluid therefrom is retarded by a ball valve 660. Thus, too energetic movement of the cam bars in either direction is avoided.

The mask plate 150 (Figs. 9 and 15a) which lies between the inflatable portion 140 and the solid rubber portion 148 of the pad is moved automatically longitudinally of the pad to an extent depending on the size of the sole. The smaller the sole the greater the extent of movement. Also, the distance between the mask plate and the sole to which it is automatically moved may be varied for different styles of shoes, that is, to produce more or less wrap of the sole during the sole-attaching operation.

The shape of the mask plate 150 for the left shoe is indicated in dotted lines in Fig. 9. This plate is arranged to slide lengthwise of the pad in the direction of the longitudinal median line of the forepart of a left sole, being guided by screws 684 which pass through the top plate 152, into the forepart portion 84 of the pad box and through slots 686 in the mask plate. The mask plate is further guided by screws 688 which engage notches 690 in opposite sides of the mask plate, the screws being also threaded into the pad box 84. At each of the rear corners of the mask plate 150 (Fig. 6) there is a pin 692 which is engaged by a square head 694 on a guide rod 696 sliding in a hole bored lengthwise of the pad box. On the rod between the bottom of the hole and the head 694 of the rod is a compression spring 698, the spring serving to retract the mask plate after each operation.

The mask plate is moved into its proper operative position by downward movement of the toe gage carriage 276. For this purpose, a pair of bars 700, 702 (Figs. 11, 12 and 15) are slidably mounted in the head frame 172 for longitudinal movement parallel to the plane of movement of the mask plate and so that their lower ends will engage the rear edge of the mask plate near its opposite corners. To impart downward move-

ment of the toe gage carriage 276 to the bars 700, 702, their lower edges have notches 708 which engage upwardly extending fins 708, 710 (Fig. 12) on a transverse bar 712 each end of which is secured to a slide 714 mounted in the toe gage carriage 276 for limited movement toward and from the pad. Each slide 714 is connected by a link 716 to a downwardly projecting arm 718 (best shown at the left of Fig. 11) on a transverse shaft 720 journaled in the end portions 278, 280 of the carriage. On the right-hand end of the shaft 720 is fixed an arm 722 which may be swung to rock the shaft and move the two slides 714 simultaneously to change the location of the fins 708, 710 with respect to the carriage 276 and hence to vary the position to which the bars 700, 702 are moved as the carriage moves toward the pad. The bars, of course, engage the mask plate and move it to a corresponding position, the movement of the carriage being controlled by the form 156. The arm 722 is held in adjusted position by a spring plunger having a thumb head 724, the plunger engaging between teeth formed on a segment 726 secured to the end wall 278 of the carriage.

The rear gage mechanism (best shown in Figs. 4, 17, and 27 to 30) comprises a supporting plate 730 pivoted at 732 to one end of a broad lever 734 fulcrumed at 736 to ears on a bracket 738 secured to the base 50. To operate the lever to move the support up and down, the lever is engaged between its ends by mechanism (Fig. 17) comprising a fluid-operated piston 740 in a cylinder 742 constituting a motor M—7. Above the piston is a plunger 744 guided through a fixed sleeve 746 and engaging a roll 748 on the lever 734. Threaded on the outside of the sleeve 746 is a nut 750 the lower end of which is in the path of the piston 740 to limit its upward movement which can be varied by turning the nut 750. For convenience in turning the nut, a sprocket 752 is secured to the nut and a sprocket chain 754 leads to another sprocket 756 on a vertical shaft 758 mounted in bearings on the frame, the upper end of the shaft carrying a handwheel 760 located adjacent to the operating station (Fig. 1).

In the bottom portion of the cylinder 742 (Fig. 17) is a sliding spool valve 762 held to the left by a spring 764 in a chamber having a vent 766, this valve being designated generally by the symbol V—1. In the position shown, fluid supplied through a pipe 768 will pass through a port 770 and raise the piston 740 and, when fluid pressure from a pipe 772 is admitted to a passage 774 when the piston is raised, the valve 762 will be moved to the right against the spring 764 to close the pipe 768 and cause the port 770 to communicate with an exhaust pipe 776. The weight of the support 730 (Fig. 4) will then cause the plunger 744 and piston 740 to descend. The inlet pipe 768 has a restricted passage at 778 to prevent the support from being raised too quickly.

The support 730 is guided in its upward movement (Fig. 4) by a slotted plate 786 fixed to a cylinder 788 to be described. A slot 790 in the plate is engaged by a roll on a pin 792 carried by ears on a bracket 794 fixed to the support so that as the support is raised the roll follows the slot 790 and determines the path of movement of the upper end of the support 730. The slot 790 is curved, as shown, to cause movement of the upper end of the support as it is raised first nearly vertically, then outwardly to avoid interference with rotating parts of the machine, then inwardly to cause open-ended curved slots 796 in

plates 798, 800 (Fig. 27) to engage long rolls 802 on screws 803 fixed on opposite sides of the rear portion 90 of the pad box (Fig. 1). The plates 798, 800 having the slots 796 are loosely pivoted (Fig. 29) on transverse shafts 804, 806, as are also hub members 808, 810, the plates being held from rotation with respect to the hub members by bolts 812 (Fig. 27) so that the hub members move with the plates when the slots engage the rolls 802. The hub members 808, 810 (Fig. 29) carry sole gage arms 814, 816 which swing from their inoperative positions shown in Fig. 4 to their operative positions shown in Figs. 27 and 29 where their free-ends lie over the rear portion of the pad and the sole gages 818 carried thereby are on the pad. These sole gages are preferably of the heightwise collapsible type disclosed and claimed in Letters Patent of the United States No. 2,186,961, granted January 16, 1940, on my application.

The gage arms 814, 816 each have upstanding ears 822, 824 in which is a fixed pin 826 on which are slidably mounted ears 828, 830 on shoe gage arms 832, 834. On each arm is a shoe gage 836 secured at 838 to the arm and having a downwardly and inwardly inclined surface 840 for engaging a shoe in the region of the breast line and to guide the shoe into proper relative position to the sole held by the sole gages 818. Preferably each shoe gage arm 832, 834 is held normally raised by a leaf spring 841 (Fig. 27) secured at one end to the sole gage arm and bearing at its other end on the shoe gage arm to hold the shoe gages 836 raised slightly from the sole gages. Pressure of the shoe will, of course, move the shoe gages 836 against the spring 841 into contact with the sole gages 818.

To provide independent adjustment of the shoe gages 836, 838 (Fig. 29) toward and from each other relatively to the sole gages 818, screws having thumb heads 842 are threaded into the gage arms 832, 834 and are held from longitudinal movement by collars 844 thereon which engage grooves in heads on the outer ends of the pins 826, 828. Turning of each thumb head therefore will adjust its shoe gage 840 toward and from the other shoe gage and relatively to its associated sole gage.

The rear shoe and sole gages at opposite sides of the pad are moved bodily and simultaneously toward each other to engage the sole resting on the pad by rotation of the shafts 804, 806. For this purpose the shafts are provided with deep grooves or threads 846 of steep pitch, the thread on the shaft 804 being left-handed and the thread on the shaft 806 being right-handed (Fig. 29). Each hub member 808, 810 has mounted therein (Fig. 30) a plunger 848 the lower end of which fits the groove 846 and is held in place by a spring 850 seated in holes bored in the plunger and in a screw 852 threaded into the hub portion 808, 810. By turning the screw the tension of the spring may be varied. Preferably the walls of the grooves 846 flare outwardly and the groove-engaging ends of the plungers are tapered to fit the grooves. The spring thus prevents any lost motion between the plungers and the grooves or threads in the shafts. Clockwise rotation of the shafts 804, 806 (Fig. 27) will move the hub members 808, 810 and consequently the gage arms toward each other. For this purpose a shaft 854 is journaled in the support 730 (Fig. 29) and has fixed thereto at each end a gear 856 which meshes with an idle gear 858 which in turn engages a pinion 860 fixed on the outer end of each of the

shafts 804, 806 so that the shafts are rotated in unison in the same direction when the shaft 854 is turned. To turn the shaft, a pinion 862 fixed on the left-hand end thereof is engaged by a rack 864 (Fig. 28) which is secured to the upper end of a piston 866 working in a cylinder 868 designated as motor M-8. The cylinder is shown as integral with a valve casing 870 which is secured to the support 730 at 871 (Fig. 27). In the casing is a slide valve 872 having a reduced portion 874, this valve being designated generally as V-2. The lower end of the casing 870 (Fig. 29) is bored to a larger diameter, and against the shoulder thus formed a disk 876 bears, being held in that position by a compression spring 878 which also sustains the valve against an opposing lighter compression spring 880 disposed over a reduced portion 882 of the valve between the upper end of the valve and the casing. An operating rod 884 connected to the valve passes through the upper end of the casing and has at its upper end a knob 886 conveniently located for the operator. The normal position of the valve 872 is determined by contact of the disk 876 with the shoulder on the casing under the influence of the spring 878. Upward movement of the valve against the spring 880 is limited by contact of the reduced portion 882 with the top of the casing 870 and downward movement of the valve is limited by contact of a stem 888 on the disk with a plug 890 in the bottom of the casing which is provided with a drain pipe 892 to take care of oil leakage and to prevent the valve from being "air bound." The casing 870 has four ports 894, 896, 898 and 900. The port 894 (Fig. 28) is connected by a passage to the top of the cylinder 868 above the piston 866; the port 896 is connected to a pressure supply line 902 (Fig. 29); the port 898 is connected by a pipe 904 to the bottom of the cylinder 868; and the port 900 is connected with another pressure supply line 906. In the normal position of the valve 872 both ports 894 and 898 are closed and the gages locked against movement. When the valve is pushed down by hand or by fluid pressure in the line 906, the port 894 will be connected to pressure line 902 and the piston 866 will move the rack 864 down, causing rotation of the shafts 804, 806 to move the gages toward each other. When the valve is pulled up, the pressure line 902 will be connected through the port 898 to the pipe 904 leading to the bottom of the cylinder 868 and the rack 864 will be moved up to separate the gages. When pressure is applied to the port 900 by the line 906, the valve will be automatically depressed by that pressure to open the port 898 to the line 904 and allow fluid to pass to the bottom of the cylinder to separate the gages.

After a right sole has been located and attached to a right shoe and the turret indexed, the machine stops with the parts in position for a left shoe, as shown in Fig. 15. The plunger 330 is acting to advance the carriage 276, causing the forks 235, 236 of the form toe gage to engage the struts 168, 168' and shift the gage to the right and to correspondingly shift the shoe and sole toe gages 275, 274 to the right.

During the previous withdrawal of the gages, the lever 618 (Fig. 9) was actuated as described to lower the left-hand form ball gage bar 542 and raise the right-hand one 540, thus setting the form ball gages 574, 576 opposite the struts 162', 164' against which they are now being urged by the action of the cam bars 304, 306 operated by the plunger 662. The sole ball gage bars 482, 490

have been lowered by the action of the motor M-4 to bring the screws 626 against the abutments 824 of the form ball gage bars 540, 542 to locate the sole ball gages 470, 472 opposite the end of the ball line of the largest left sole.

Supposing now a left outsole O of some intermediate size (Fig. 15) is placed on the pad with its toe end against the wires 398 of the sole toe gage 274 and the treadle A depressed to move the form up, this will allow the sole toe gage to move longitudinally of the pad toward the operator, pushing the sole with it, and the ball gages will approach the sole until all the gages are in contact therewith, thus locating the forepart of the sole in proper orientation to the forepart of the pad.

The operator will now depress the knob 886 of valve V-2 (Fig. 29) to cause the rack 864 to descend and move the breast-line sole and shoe gages toward the sole until the sole gages 818, 818 engage the opposite edges of the sole at the ends of the breast line. The direction of the longitudinal median line of the forepart of the sole with respect to the pad has thus been so determined by the forepart gages that if the breast-line sole gages move equally and oppositely, as they do, the direction of the longitudinal median line of the rear part of the sole will be brought into the proper relation to that of the forepart even if the sole is distorted. The sole is now ready to receive a shoe S which is placed on the sole with its toe end against the diverging surfaces 350, 352 of the shoe toe gage 275. This locates the toe end of the shoe properly with respect to the toe end of the sole. The rear part of the shoe engages the breast-line shoe gages 836 and is guided by the inclined surfaces 840 into proper relation to the rear part of the sole held by the breast-line sole gages 818.

Pressure is now applied to the shoe by mechanism shown in Figs. 4 and 31 to 38. To apply pressure to the forepart of the shoe, a bail 910 is provided in the loop of which a toe pad 912 is mounted. The ends of the bail are pivoted at 914 one to each of the rear ends of an equalizing lever having parallel parts 916, 917 (Fig. 35). When not in use, the bail 910 can assume the dotted-line position shown in Fig. 31, a notch in each arm of the bail then engaging a pin 918 in the side of the forepart 84 of the pad box, the pin preventing rearward and downward movement of the bail.

To apply pressure to the rear cone of the last, a bail 920 has one of its ends pivoted at 922 to the front end of the part 916 of the equalizing lever and its other end to the front end of the part 917 of the lever. The pivots 914 (Fig. 31) extend through openings 923 formed in the side walls 78, 80 of the bracket 68 and the front portions of the side walls are bent away at 925 to give access to the pivots 922 and the lever. The bail 920 is swung to its inoperative position by a tension spring 924 (Fig. 4) connected at one end to the bail and at the other end to the bracket wall 78. When in this position, a notch in each side of the bail engages a pin 926 on the side of the part 84 of the pad box. A link 928 (Fig. 31) is pivoted at 930 to the bail 920 and has in its other end a slot which engages a pin 932 on the bail 910. When the bail 920 swings rearwardly in response to the spring 924, the front end of the slot engages the pin 932 and pushes the bail 910 to its inoperative position shown in dotted lines in Fig. 31. When the bail 920 is swung rearwardly over the rear end of the shoe, the bail

910 will swing forward by gravity and, if it should cling to the pin 918, further rearward movement of the bail 920 to cause the rear end of the slot in the link 928 to engage the pin 932 will cause the bail to swing forwardly.

In the top portion of the bail 920 (Fig. 32) is formed a horizontal guideway in which is mounted a sliding block 934 which is connected by a link 936 to a lever 938 pivoted at 940 to the bail and having a handle 942. A tension spring 944 is connected at one end to the lever 938 below its fulcrum and at its other end to the bail so that normally the slide 934 is held by the spring at the right-hand end of its travel as viewed from the front of the machine. By grasping the handle 942 the operator may move the slide 934 into position over the last whatever may be the lateral position of the shoe on the pad as determined by the rear shoe gages. To afford a square bearing on the last cone, a semi-circular bearing member 946 (Fig. 33) is mounted in a complementary slot in the slide 934 for movement about a center located on its straight or last-engaging face, the member having a curved slot engaged by a pin 948 to hold it in place but permitting it to turn so that its straight face will bear squarely on the cone of the last. To locate properly the member 946 lengthwise of the last, a finger 950 is pivoted thereto at 951 so as normally to assume a position in line with the last-engaging face of the member. The bail 920 is swung forwardly until the operator observes that the finger 950 will clear the projecting front cone C of the last when the bail 920 moves down to apply pressure to the last. If the finger engages the cone of the last, it can swing up and no harm is done. Preferably a spring plunger 952 is arranged in the member 946 to engage a flat end on the finger 950 and hold it in a horizontal position but permitting it to be moved into a vertical position where it will be held by pressure of the plunger upon a flat top face on the finger.

When the bail 910 swings forwardly, it is stopped by engaging a pin 954 which is positioned in accordance with the length of the shoe. For this purpose the pin is carried by an arm 956 of an angle lever pivoted at 958 to the bracket wall 80, the other arm 960 of the lever being connected by a link 962 to a lever 964 pivoted at 966 to the wall 80 and having in its upper end a slot engaging a pin 968 on a slide 970 which has ratchet teeth 972 on its lower side. A pawl 974 is pivoted at 976 to the wall 80 and is urged by a tension spring 978 to engage the teeth 972. The pawl 974 has an arm 980 which is engaged by the bail 910 when in its inoperative rearward position to hold the pawl 974 out of engagement with the teeth on the slide 970 so that the slide is free to be moved to position the stop pin 954. A tension spring 982 connected at one end to the pad box portion 84 and at the other end to the arm 956 moves the pin and slide rearwardly when the pawl is released.

To hold the toe pad 912 in the position determined by the pin 954 when pressure is applied to the shoe, the top plate of the pad box (Fig. 31) is provided with a toothed plate 983 and on the inner side of the bail 910 (Fig. 34) is a pawl block 985 arranged to slide in a slot 987 in the bail and normally held by a tension spring 989 (Fig. 31) at the bottom of the slot. When pressure is applied to the shoe forepart by downward movement of the bail 910, the block 985 engages the plate 983 and prevents movement of the toe pad 912 longitudinally of the shoe. The spring 989 permits the

mechanism thus to operate upon foreparts of varying heightwise extent.

When the gage carriage 276 moves down, the slide 970 is engaged by the offset lower end of a bar 984 (Fig. 6) mounted to slide in the head frame 112. The bar is held in retracted position by a tension spring 986 connecting its upper end to the frame 112. In the upper edge of the bar 984 is a long notch which is engaged by a downwardly projecting rib 988 on a slide 990 (Fig. 11) mounted on the lower side of the top plate 282 of the gage carriage 276 for movement longitudinally of the bar 984. When the toe carriage moves down, the rib 988 engages the lower end of the notch and moves the bar 984 down to engage the slide 970, thus positioning the stop pin in accordance with the length of the shoe since movement of the carriage is so determined by engagement of the form toe gage 234 with the form 156. When the bail 910 swings into operative position over the toe of the shoe, the pawl 974 is released and locks the stop pin 954 against rearward movement, thus causing the bail 910 to be arrested with the toe pad 912 located over the forepart of the shoe in accordance with the length thereof.

To vary the position automatically assumed by the toe pad under different conditions of work, a lever 992 (Fig. 11) is loosely pivoted at its lower end on the shaft 720 and has at its upper end a spring plunger 994 which engages between teeth formed on a segmental plate 996 secured to the end wall 280 of the toe gage carriage. An intermediate portion of the lever 992 extends through an opening in the end wall 280 and is connected by a link 998 to the slide 990. By releasing the plunger 994 and swinging the lever, the initial position of the rib 988 may be varied and hence the movement imparted to the bar 984 by movement of the carriage.

The double lever 916, 917 has its front ends connected integrally by a cross-piece 1000 which bows downwardly and has its rear ends similarly connected by a similar cross-piece 1002. Between its ends each part of the lever (Fig. 35) is pivoted by a pin 1004 to a square block 1005 arranged to slide in a slot 1006 (Fig. 31), one of the slots being in the side wall 78 and the other in the side wall 80 of the bracket 68. Each pin 1004 is connected by a link 1008 to one of the branches 1010 of a forked lever fulcrumed at 1012 between the side walls 78, 80 of the bracket. An arm 1014 of the lever carries a roll 1016 which is engaged by a plunger 1018 in the cylinder 788 previously mentioned as supporting the slotted plate 786 which guides the rear gage support 740 (Fig. 4). The cylinder and plunger constitute motor M-9. Fluid supplied under pressure to the cylinder through a pipe 1020 (Fig. 3) will operate the forked lever 1010, 1014 to move the pivots 1004 of the equalizing lever 916, 917 downwardly in the slots 1006 and cause the bails 910, 920 to apply pressure equally to the two ends of the shoe.

To raise the bails 910, 920 a tension spring 1022 (Figs. 4 and 31) is connected at one end to a downwardly extending arm 1023 on the forked lever 1010, 1014 and at the other end to the sleeve 60 on the column 58 (Fig. 4). The plunger 1018 is returned by a tension spring 1024 connected to a pin on the upper end of the plunger and to a hook on the lower end of the cylinder.

The pressure obtained by operation of the plunger 1018 is maintained as follows: The sleeve 102 which connects the branches of the U-shaped lever 1016 to the rear part 90 of the pad box

through the links 96 (Fig. 36) contains an inner sleeve 1026 (Fig. 37) arranged for limited movement with respect to the sleeve 102 by a pin 1028 in the sleeve 102 which engages a slot in the inner sleeve 1026. The inner sleeve is normally held raised with the pin 1028 against the lower end of the slot by a tension spring 1030 connected between a pin on the sleeve 102 and a pin on the inner sleeve 1026. Between the two sleeves is a double or U-shaped wedge 1032 each branch of which has an upper inclined surface 1034 which engages a complementary inclined surface on the end of the sleeve 102 and a lower surface 1036 which is perpendicular to the longitudinal axis of the inner sleeve and rests on a lateral projection 1038 of that sleeve so that action of the wedge can move the inner sleeve 1026 with respect to the sleeve 102 to a limited extent against the tension of the spring 1030. Inside the inner sleeve 1026 is a strut 1040 which slides freely therein and is pivoted at its lower end to the crossbar 1000 of the equalizing lever. The crossbar has a slot 1042 (Fig. 37) in which the flattened lower end of the strut 1040 is located and in which it is held by a pin 1044. A flat face on the strut is provided with teeth 1046 which are engaged by a pawl 1048 pivoted at 1050 to a projection 1052 on the inner sleeve 1026. From one side of the upper end of the pawl a pin 1054 projects (Fig. 36) into a groove 1056 formed on one branch of the wedge 1032. The groove extends a short distance parallel to the surface 1036 of the wedge and then opens upwardly at 1058. Initially with the wedge withdrawn (Fig. 37) the pin 1054 engages the groove 1056 and holds the pawl 1048 out of engagement with the teeth of the strut against the action of a compression spring 1060 arranged between the upper end of the pawl and the inner sleeve which has an opening 1062 below the spring to permit the pawl to engage the teeth on the strut. Normally the cross-piece 1000 rests against the lower end of the sleeve 1026 but, when pressure is applied to the shoe, the cross-piece descends, drawing down with it the strut 1040 while the sleeves and wedge remain in position because they are connected to the pad box. When the wedge is advanced, that is, moved to the left in Fig. 37, the groove 1056 passes beyond the pin 1054 which is then free to move in the space 1058. The pawl then swings in response to the spring 1060 toward the teeth 1046 of the strut 1040 and will engage usually in the space between two of the teeth. Further movement of the wedge, however, will move the inner sleeve which carries the pawl downwardly and cause the pawl to engage one of the teeth, thus maintaining all the pressure obtained by the action of the plunger 1018.

To maintain the pressure applied to the forepart of the shoe similar sleeve and wedging mechanism is provided the parts of which correspond to those just described and are indicated by the same numerals primed. The sleeve 102' (Fig. 34), however, in the case of the forepart pressure-maintaining mechanism, is directly pivoted to the side walls 78, 80 by extensions of the pins 108 which support the rear end of the U-shaped lever 106. The wedges 1032, 1032' are withdrawn (Fig. 35) by bars 1066, 1068, the bar 1066 being connected at one end to the wedge 1032' and the bar 1068 to the wedge 1032. The wedges are moved to operative position by tension springs 1070, 1072, the spring 1070 extending between a pin on the bar 1066 and a pin on one branch of the U-shaped lever 106, and the spring 1072 connecting a pin on the bar 1068 with a pin on the other

branch of the lever 106. Therefore, when the bars are released, the springs 1070, 1072 act independently, one to advance the wedge 1032' and the other to advance the wedge 1032. To retract the wedges the rear ends of the bars are slotted to receive pins 1074, 1076 on an arm 1078 (Fig. 34) pivoted at 1080 to a bracket 1082 on the part 84 of the turret. Another arm 1084 fast to the arm 1078 and on the same pivot 1080 is connected to 10 a vertical rod 1086 which at its lower end is guided through a hole in the gear 62 and has a collar 1088 thereon to limit its downward movement. Upward pressure on the rod 1086 will withdraw the wedges against the action of their springs and, when 15 upward pressure on the rod is counteracted, the rod will move down, causing the pins 1074, 1076 to move forwardly and allow the springs to operate the wedges. After the wedges are inserted, the pins 1074, 1076 may move farther forward in 20 the slotted ends of the two bars 1066, 1068 and allow the rod 1086 to descend until the collar 1088 engages the gear 62, or rather a cam plate thereon to be described.

It will be understood that the pressure-applying and pressure-maintaining mechanism above 25 described is duplicated for each of the eight stations of the machine.

To push up on each of the rods 1086 as it comes to the operating station, there is located below the lower end of the rod a fixed cylinder 1090 having a head at each end. In the cylinder is a piston 1092 on the upper end of which is fixed a small plunger 1094 which extends through the upper head of the cylinder and which, upon upward movement of the piston, will engage the rod 1086 and lift it to retract the wedges. On the lower end of the piston is a plunger 1098 larger than the plunger 1094 and extending through the lower head of the cylinder. This fluid motor is 30 referred to as motor M-10. Fluid under constant pressure is maintained in the lower end of the cylinder 1090 through a pipe 1098 to hold the wedges retracted and at times fluid pressure is supplied through a pipe 1100 to the upper end of the cylinder to allow the wedges to operate. This pressure, however, need be no more than that supplied to the lower end of the cylinder because the effective area of the top of the piston is greater than that of the bottom of the piston, 35 the plunger 1094 being smaller than the plunger 1098. When the piston 1092 is fully depressed by pressure in the line 1100, it allows pressure to pass to a line 1101 referred to later.

The shoe and sole having been relatively positioned, pressed firmly down upon the pad and locked by the wedges in that position, as already 40 explained, the lower portion 146 of the pad is inflated with water under pressure to insure that all parts of the sole, particularly its peripheral portion, will be forced up against the shoe bottom. For this purpose each pad is provided with a pad-inflating device such as that more fully described in my Letters Patent No. 2,356,756 above referred to. The inflating device comprises a casting 1102 (Fig. 4) bolted at 1105 to the rotating sleeve 60 and having a cylindrical portion 1106 in which is a piston 1108. A passage 1110 leads from the bottom of the cylinder, and this passage, in the position shown in Fig. 4, leads to a peripheral groove 1112 in the turret post 58, the groove being supplied with oil under pressure through a port 1114 by the pump P-2 through a line 1115 (Fig. 3).

Oil entering the cylinder 1106 passes through a 45 valve V-3 (Fig. 5) which comprises a sleeve 1116

having a large port 1118 on the side next to the cylinder and a smaller port 1120 on the opposite side, the ports alining with the passage 1110. In this sleeve is a spool valve having a large head 1122, a smaller head 1124 joined by a portion of still smaller diameter and a stem 1126 extending down through a hole in the gear 62. The sleeve 1116 has a portion of restricted diameter fitting the small head 1124 of the valve and the restricted portion is cut away at 1128 on the side next to the cylinder 1106 so that when the valve is in the position shown in Fig. 5, in which it is depressed by a spring 1130, it will permit passage of the fluid from the cylinder to the lower end of the sleeve 1116 while the head 1122 completely closes the small port 1120, thus preventing pressure fluid from passing from the turret post through the valve. When the valve is raised against its spring 1130, the head 1120 opens the port 1120, and the portion 1124 enters the restricted portion of the sleeve to prevent downward passage of the liquid which then passes through the ports 1118 and 1120 to the cylinder 1106 and, since the fluid pressure on the large head 1122 of the valve is greater than that on the small head 1124, the valve is maintained in this position by this differential pressure. The piston 1108 has a rounded top portion 1132 which engages a resilient bag 1134 of rubber or like material enclosed in a head 1136 detachably secured to the cylinder. The bag 1134 is connected by a tube 1138 to the inflatable portion 146 of the pad. To fill the bag and the pad with water, a source of supply may be connected to a cock 1140 in the tube 1138. Compression of the bag 1134 by upward movement of the piston 1108 will, of course, force water into the pad 146 to inflate it and thus apply the desired further pressure to the shoe bottom. As shown in Fig. 4, pressure is being maintained on the shoe bottom and this condition is continued at seven of the eight stations in the construction shown; that is, bag pressure is relieved on one shoe and applied to another at the first or operating station at the front of the machine.

It will be seen from Fig. 3 that the peripheral groove 1112 in the turret post extends from station #2 to station #8, the groove being supplied with oil under pressure by the pipe 1115 from pump P-2. When a shoe under pressure reaches the first or operating station (Figs. 3 and 5), the passage 1110 comes opposite a port 1146 in the turret post through which at the time no pressure is being applied. This relieves the differential pressure on the valve heads 1122 and 1124 so that the valve opens in response to the spring 1130 and discharges the pressure fluid under the piston 1108 through passage 1110, large port 1118, under valve head 1122 directly to the sump, and closes the small port 1120 leading from the turret post.

The pad at the first or operating station is so located that the stem 1126 of the valve and its inflating device is over a plunger 1148 in a stationary cylinder 1150 constituting motor M-11 (Fig. 5). Formed in the cylinder block is a passage 1152 communicating with a passage 1154 in the turret post 58, the passage leading to the port 1146 at the operating station. The passage 1152 is supplied with fluid from pump P-1 in a manner to be described. The plunger 1148 is normally depressed by a spring 1156 and is lifted to engage the stem 1126 and raise the valve V-3 by pressure introduced under the plunger from a pipe 1158 through a check valve 1159 (Fig. 43) which prevents flow backward or away from the cylinder 1150. The pipe 1158 receives pressure

fluid from the ball-operating cylinder 188 when its plunger 1018 has reached the upper portion of its travel in applying pressure to the shoe. This pressure is effective to operate the plunger 1148 only if a passage 1160 from the cylinder is closed. This is done by a spool valve 1162 working in a cylinder 1164 designated as valve V-4. The valve is held with its exhaust port 1166 open by a spring 1168 and the port is closed by pressure introduced through a pipe 1170 which receives pressure at the time when the ball-operating plunger 1018 is caused to ascend by depression of the treadle B. When there is pressure in the passage 1152, the fluid passes through a duct 1172 to the right-hand end of the valve 1162 to assist the spring 1168 to open the valve and allow exhaust of the fluid under the plunger 1148 through the pipe 1166.

Various other valves controlling operation of the fluid motors described will be best understood from the diagrammatic views shown in Figs. 43, 44 and 45 in connection with which the valve constructions can be adequately described. Fig. 43 indicates the position of the operating instrumentalities just after the turret has been indexed and the forepart gages are about to move over the pad. The pumps P-1 and P-2 are both directly driven by the electric motor M (Fig. 3) and both receive oil through a branch pipe 1174 which dips into the oil in the base of the machine or sump. Pump P-1 supplies oil under pressure through the pipe 1176 to the fluid-operated indexing motor 74 and through a smaller pipe 1178 to a hand valve V-5 which comprises a cylindrical casing 1180 in which is a slide-valve 1182 having three heads and two reduced portions. The casing has two exhaust ports 1184, 1186. The valve is depressed by a spring 1188 and may be raised by operation of an angle lever 1190 pivoted to the casing 1180 and provided with a push knob 1192. The valve may also be raised automatically by pressure introduced at the bottom of the valve through a line 1194. In its normal depressed position (Fig. 43) the upper reduced portion of the valve 1182 allows fluid in the line 1178 to pass to the line 518 to operate motors M-2, M-3 and M-5, to move the forepart gages to operating position, and the line 518 is also connected through a flexible connection 1196 to line 302 leading to the port 896 of the valve V-2. This valve at the time being in neutral position, nothing is operated by it. Line 1178 is also connected by the line 778 to the valve V-1 which, being then open, allows fluid to pass through line 780 to motor M-7 to raise the rear gage carrier 730. From the line 778 a branch 1198 supplies fluid to two treadle valves V-6 and V-7, and a branch line 1200 from the line 1178 is connected to the line 1098 to supply fluid to the motor M-10 to hold the wedges out. This line 1200 is extended to a power-operated valve designated generally by the symbol V-8 which determines whether fluid will pass to line 232 or line 238, thus determining the direction of pressure on the arm 226 of motor M-1 and whether the form 156 will be moved up or down under control of the treadle A, as above explained.

As shown in Fig. 43, depression of treadle A will move the form down as required for locating a sole for a right shoe. The valve V-8 (Fig. 46) comprises a casing 1202 in which is a sliding double spool valve member 1204 which is operated by a pitman 1206 connected to a crank on the lower end of a shaft 1208 which carries a gear 1210. This gear has a 4 to 1 ratio to the gear 62 with which it meshes and thus, at each indexing

of the turret, the gear 1210 is given a half revolution and the valve V-8 is shifted from the position shown in which the line 1200 is connected to the line 238 and the line 232 is exhausting to a position in which line 1200 is connected to the line 232 and line 238 is exhausting or vice versa. In the line 1200 is a hand valve V-9 having a handle 1211 arranged conveniently for the operator (Fig. 3) which may be operated to cut off the supply end of line 1200 and exhaust the portion leading to valve V-8 to cause the form 156 to return to its initial position irrespectively of the direction in which it may have been moved. The pressure in lines 1176, 1178 and connected lines is maintained by a pressure-control valve designated generally by the symbol C-1 which will be later described.

Supposing now that the parts about to move in Fig. 43 have moved to their operating positions, that is, the motors M-2, M-3 and M-5 have operated to move the forepart gages over the pad as far as the form 156 permits and the motor M-7 has raised the rear gage carrier and caused the rear gages to swing over upon the rear end of the pad in open position, a sole will be placed upon the pad and treadle A will be operated to move the form in the proper direction to allow the toe and ball-line gages to engage the sole. The valve V-2 is then depressed to connect the port 896 with the port 894 and admit pressure fluid from the line 902 above the piston of motor M-8, causing the rack 864 to go down and move the breast-line sole gages 818, 820 equally and oppositely to engage the sole. The shoe gages are now in position for locating a shoe relatively to the sole and the mask plate 152 has been moved longitudinally of the pad to the proper position with respect to the positioned sole. The operator places a shoe on the sole to be positioned by the shoe gages, grasps the handle 942 with his left hand while holding the shoe with his right, swings the ball 920 over the rear end of the last and moves the handle sidewise to locate the abutment 946 over the rear cone of the last. The ball 910 falls into position over the toe of the shoe and is arrested in proper longitudinal position by the stop pin 954 which has been set in accordance with the size of the sole.

Before the application of pressure to the shoe by depression of the treadle B is described, several valves which take part in the operation will be briefly explained in connection with Figs. 43 and 46. The pressure in a line 1212 from pump P-2 is controlled by a pilot relief valve, designated as a whole by C-2 (Fig. 43), which consists of a differential piston 1214 working in a cylinder 1216. A bypass 1218 opens below the smaller end of the piston and leads to a chamber above the larger end. Flow through the bypass is controlled by a screw 1220. Above the larger end of the piston is an opening which is closed by a conical valve 1222 held in place by a spring 1224 the tension of which is controlled by a screw 1226. When the pressure in line 1212 on the lower end of the piston 1214 exceeds the pressure for which the spring 1224 is set, the valve 1222 lifts and allows fluid to exhaust at 1228. The piston 1214 then rises, opening a line 1230 leading to a pressure control valve C-3 which is set for a lower pressure and controls pressure in a line 1232 the purpose of which will be later described.

The line 1212 provides a loading pressure in place of springs on valve C-1 and on a series of valves arranged in groups, V-10, V-11, V-12 and V-13 being in one group and V-14 and

V-15 in another group. The valve V-13 is physically located between V-12 and V-14 but is supplied with loading pressure from another source, as will be explained. A block 1240 (Fig. 2) contains the first group and a block 1242 the second. Along the top of the block 1240 (Fig. 3) is a manifold 1244 connected with all of the valves of the first group except V-13 and along the top of the block 1242 is a manifold 1246 for the second group. The line 1212 is connected to the left-hand end of the manifold 1244, continues along the top of the valves on the outside, is connected to the right-hand end of the manifold 1246, and then leads to the top of valve C-1. This construction is the equivalent of that shown in the diagram (Fig. 46) where the upper end of each valve except V-13, is connected to line 1212, it being understood that the valves are vertically arranged in the machine but are laid down in the diagram better to show their construction. The terms upper and lower or top and bottom as used herein refer to the actual position of the valves in the machine.

The valve V-10 is a spool valve in a casing, a reduced portion of the upper head of the spool being loaded with fluid pressure from line 1212. The lower head has a stem 1250 having a reduced portion forming a shoulder, and the reduced portion is connected to a piston in a cylinder, constituting motor M-12, which is connected by a line 1252 to the valve V-8 operated by treadle B. In its normal or lower position there are four ports between the heads of valve V-10, a small port connected to the line 1100 leading to the upper end of the cylinder 1090 of the wedge-controlling motor M-10 (Fig. 34), a large port connected to a pressure supply line 1254 leading from the pressure control valve C-1, a discharge port connected by a passage 1256 to a port in the valve V-11, and an exhaust port 1258 leading to the sump.

When, by depression of the treadle B, valve V-8 is moved to admit pressure from the line 1198 leading from line 1178 to the line 1252, the motor M-12 operates to raise the spool of valve V-10 which is latched up by a spring plunger 1260 in a cylinder designated as motor M-13, the plunger engaging under the shoulder on the stem 1250 to hold the valve raised and being arranged to be retracted by pressure in a line 1262 controlled by the valve V-14. When the valve V-10 is raised, the port to line 1100 and the exhaust port 1258 are closed and the line 1254 is connected through the passage 1256 to the valve V-11.

From the line 1252 leading to the motor M-12 is a branch line 1264 leading to a pair of motors M-14 and M-15 exactly like motor M-12 and acting simultaneously to raise valves V-14 and V-15 in response to pressure in line 1264. Valve V-14, which is pressure loaded in a manner similar to valve V-10, comprises a double spool in a casing. The spool, when in lowered position, connects, by the space between its upper and middle heads, a line 1266 branching from the line 1020 with the line 1262 to hold the latch of V-10 in released position. The middle head of V-14 closes the line 1101 from the wedge-retracting motor M-10 and by the space between its middle and lower heads opens to exhaust a line 1268 leading to the lower end of valve V-11. When raised, the valve V-14 opens the line 1262 to exhaust between its upper and middle heads, closes the branch line 1266, and by the space between its middle and lower heads connects the

line 1101 from the motor M-10 to the line 1268 leading to the bottom of valve V-11.

The valve V-15 is a single spool valve which is pressure loaded in the same manner as valves V-10 and V-14. In its lowered position (Fig. 46), the valve closes by its upper head the line 1100 leading to the top of the wedge motor M-10 and opens to exhaust by the space between its heads the line 1194 leading to the bottom of valve V-5. When raised (Fig. 44) the valve V-15 connects by the space between its heads the line 1100 with the line 1194 to lift valve V-5, its lower head closing the exhaust.

The valves V-14 and V-15 are held raised by latches 1270, 1271 formed on a bar 1272 arranged to slide longitudinally and operated by a lever 1274 fulcrumed between its ends, one arm being pivoted to the bar and the other arm positioned to engage a double cam 1276 fixed on the shaft 1208 which carries the gear 1210. A compression spring 1278 between one arm of the lever and a fixed abutment urges the bar in a direction to bring the latches 1270, 1271 under shoulders on the stems of valves V-14 and V-15 to hold them up after they are raised and to locate one arm of the lever 1274 so that upon a semi-rotation of the double cam 1276 one half or the other of the cam will act to release the latches 1270, 1271. A rod or wire 1279 is attached to the lever 1274 and provided with a handle 1280 at the front of the machine (Fig. 1). By pulling on the handle the valve latches may be tripped at any time.

The valve V-14 comprises a casing enclosing a spool 1282 the upper end of which is fluid-pressure loaded from line 1212, said loading being partly counteracted by a spring 1284 extending into a hole in the lower end of the spool and engaging the lower end of the casing. In its lowered position the upper end of the spool closes an exhaust port 1285 and the space between its heads connects the passage 1256 with the line 1020 which leads to the bottom of the pressure-applying motor M-9. When raised, the valve connects the line 1020 to exhaust port 1285.

It will now be seen from Fig. 44, which shows conditions after treadle B has been depressed, that the valves V-10, V-14 and V-15 are raised as described. Therefore, pressure fluid from pump P-1 through line 1176 will pass through the pressure control valve C-1 to the line 1254 and will pass through valve V-10 and passage 1156 to the valve V-11 and thence through the line 1020 to raise the plunger 1018 of the motor M-9, thus applying pressure to the shoe.

Control valve C-1 (Fig. 46) comprises a spool piston 1288 in a cylinder 1288 having heads at both ends, the top of the piston being loaded from line 1212 and the bottom receiving pressure fluid by the line 1176 from pump P-1. When the pump pressure lifts the piston somewhat, a port to line 1254 is opened and, when flow in this line is opposed, the piston moves up and opens a port to a line 1290 leading to valve V-12 which now is in exhaust position. Pressure in the line 1020 leading to the motor M-9 is therefore limited to the loading pressure on the valve C-1, although by using a differential piston the pressure in lines 1254 and 1290 may be made more or less than loading pressure. As movement of the plunger 1018 of motor M-9 is opposed by the shoe, pressure builds up in lines 1254 and 1020 and in the passage 1256 toward the valve determined by control valve C-1 and from the passage 1256 passes into the branch 1170 to the valve V-4 which it pushes to the right against the

spring 1160 to close the exhaust from motor M-11.

Pressure in the passage 1256 also passes through a check valve 1292 (Fig. 46) to the line 1100 leading to the motor M-10 and forces the piston down to permit the wedges 1032, 1032' to go in. As the plunger 1018 of motor M-9 approaches the end of its stroke the line 1158 is opened, allowing pressure fluid to flow through check valve 1159 to raise the piston 1148 of motor M-11 to open the inflating valve 1124 (V-3) and establish communication from the turret post passage 1154 to the inflating device at the first station. When the piston 1092 of the wedge motor M-10 reached the bottom of its stroke, pressure fluid passed through line 1101 to valve V-14 and thence through line 1268 to the lower end of valve V-11. When the pressure on this valve approaches the loading pressure, the valve rises, assisted by the spring beneath it, closes the passage 1256 and opens the line 1020 to exhaust, allowing the plunger 1018 of motor M-9 to descend.

Since the volume of flow through line 1254 is now greatly reduced, the piston of control valve C-1 will be forced up to open line 1290 leading to valve V-12 which, being in exhaust position, will allow the fluid to spill out.

The pressure thus maintained in line 1100 (Fig. 44) will pass through the open valve V-15 to the line 1194 leading to the valve V-5 and will lift it, causing the line 518 connected to the motors M-2, M-3 and M-5 to be exhausted and the line 674 leading to the motors M-4 and M-6 to be connected to the pressure line 1178, thus causing these motors to open and retract the forepart gages. Pressure from the line 1178 also passes through the line 906 of the valve V-2 and, entering above its upper head, forces the valve down to open the line 904 to pressure which is conducted to the bottom of motor M-8, causing the rack 864 to move up and separate the rear or breast-line gages.

To insure that the forepart gages cannot accidentally go down over the pad again after they have been withdrawn and can go down only after the indexing movement is substantially completed, a latch 1293 (Fig. 6) is provided which engages a pin 1294 on the lower arm 510 of the lever 494 operated by the motor M-4. The latch is urged upwardly by a spring 1296 to engage the pin 1294 when the gages are fully withdrawn. The latch 1293 is on the rear end of a lever 1298 pivoted on the shaft 326, the front end of the lever being engaged and lifted by an inclined upper face 1300 of a block 1302 mounted on the portion 82 of the bracket 68 which carries each of the pad boxes. Hence, as the next pad box moves into the first station, the inclined surface 1300 raises the front end of the lever to release the latch at about the time when the valve V-15 is unlatched to allow the valve V-5 to descend and connect the motors M-2, M-3 and M-5 to the pressure line 518 to move the forepart gages down. Just as the turret is about to stop, the lever 1298 drops off the block 1302, allowing the spring 1296 to raise the latch 1293 so that when the gages are again withdrawn the latch will engage the pin 1294 and hold the gages up. The front end of the lever 1298 is laterally supported and its downward movement limited by a bracket 1304 secured to the frame 172 and having a slot 1306 in which the lever can move up and down (to a limited extent) but not sidewise.

The valve V-12 comprises a spool 1316 with a reduced stem at each end, the upper stem w-

ing in a cylindrical chamber that is pressure loaded from the line 1212 and the lower stem having two diameters with a shoulder between them. The lower end of the stem is connected to a piston working in a cylinder constituting a motor M-16 like the motors M-12, M-14 and M-15. The treadle C is connected to the valve V-7 which is similar to the valve V-6. Depression of the treadle causes pressure to flow from the lines 1178 and 1198 through a line 1312 to the motor M-16 to raise the valve V-12. Lifting of the valve V-12 closes its exhaust port 1314 and causes pressure to flow through a line 1316 to the turret post passage 1154 and thence through the open valve V-3 to the cylinder 1108 at the first station to operate the piston 1108 and inflate the pad 146. The valve V-12 is locked up (Fig. 46) by a latch 1318 pivoted to the bar 1272 and having a tail to limit clockwise movement in response to a spring 1320. When the bar was moved longitudinally to the left (Fig. 43) to lock up the valves V-14 and V-15, the spring was put under tension so that when the stem of the valve V-12 is raised the latch will engage under the shoulder on the valve stem. When the bar is moved to the right by the cam 1276, the tail of the latch 1318 prevents its turning and causes it to be withdrawn from under the shoulder.

Pressure also flows in a branch 1322 from the line 1316 to the valve V-13 which controls the bag pressure. This valve comprises a casing 1324 with a head at each end and a movable element having a stem with a piston 1326 at one end which is pressure loaded from the line 1232 the pressure in which is controlled by a valve C-3. The stem of the valve V-13 also carries a disk 1328 at the end opposite the piston, the disk closing a cylindrical chamber 1330 which receives pressure from the branch line 1322. In the middle of the stem is a second disk 1332 which, when the valve is lifted sufficiently, closes a restricted passage 1334 leading to an exhaust port 1336. In the side of the cylinder 1324 between the disks, a line 1338 is connected which leads to the valve V-1 controlling the motor M-7 of the rear gage support 730. The pressure area of the disk 1328 is somewhat less than the pressure area of the piston 1326 so that the pressure-control valve C-3 will be set for a loading pressure somewhat less than the desired bag pressure, which usually is in the neighborhood of 80 p. s. i. When the desired pressure is reached, the disk 1328 will lift slightly, allowing fluid to flow around the middle disk 1332 and out through the exhaust port 1336. As the fluid flow increases in volume, the disk 1328 is lifted farther and the disk 1332 closes the restricted passage 1334, forcing fluid to flow through the line 1338. This pressure pushes the valve V-1 to the left, as shown in the diagram (Fig. 45) against its spring 114 and opens to exhaust the bottom of the cylinder of the motor M-7, allowing the support 730 of the heel gages to move down out of the way of the turret. As influx of fluid continues into the chamber between the disks of valve V-13, pressure on the disk 1332 will force it through the restricted passage and allow the excess to flow through the exhaust port 1336, pressure still being maintained in the line 1338.

The valve C-3 is of a usual pressure-regulating type comprising a piston 1340 (Fig. 43) subjected to pressure of the overflow from the valve C-2, movement of the piston being opposed by a spring 1342 the tension of which may be adjusted by a screw and hand-wheel 1344 located adjacent to the operator (Figs. 1 and 3a). When

the pressure in line 1232 reaches the value for which the valve C-3 is set, the piston 1340 moves sufficiently to open an exhaust port 1346.

It may be helpful to recapitulate briefly the conditions described and shown in Fig. 45. Pressure passing through the check valve 1292 and the line 1100 is holding the piston of motor M-10 down so that the wedges stay in; flow from M-10 through line 1104 passes through valve V-14 to line 1268 to hold the valve V-11 in exhaust position; the line 1170 is receiving pressure to hold the valve V-4 closed but fluid pressure in the line 1316 flowing through the passage 1172 is acting to push the valve V-4 to the left, opening the exhaust of the motor M-11; pressure in the line 1100 flows through valve V-15 and the line 1194 to hold the hand valve V-5 raised, the forepart gages being thus withdrawn and locked up; and the consequent pressure in line 906 has pushed hand valve V-2 down, causing the piston of motor M-8 to move up and separate the breast-line gages.

Before the turret is indexed there should be a guarantee that the pistons of motors M-7 and M-9 are down and that the pistons of motors M-4 and M-6 are up, that is, that the heel gage carriage 730 is out of the way, that the plunger of the motor M-9 for applying pressure to the shoe is down, and that the forepart gages are open and moved up to their inoperative positions. This is accomplished by a safety line through which fluid can pass only when the parts are in the positions above indicated. Passage of pressure fluid through this safety line is utilized to withdraw an indexing pin and initiate action of the indexing motor 74.

After operating the valve V-1 through the line 1172 the pressure fluid in the line 1338 passes through a peripheral groove in the upper end of the piston 740 of motor M-7, into a line 1348 leading to a peripheral groove in the upper end of the plunger 1018 of motor M-9, thence to the center of the turret post at its bottom, then up through the post to a peripheral groove in the bottom of the plunger 662 of motor M-6, thence to a peripheral groove in the lower end of the plunger 526 of motor M-4, back down through the center of the turret post to a timing valve TV, and thence through line 1350 to a motor M-17 for withdrawing the indexing pin and operating a valve in the exhaust line from the indexing motor 74.

The parts indicated generally by the symbols TV and M-17 are built together, as illustrated in Figs. 39 to 42, the line 1350 represented as connecting them in the diagram (Fig. 45) being in fact a short passage, as shown in Fig. 39. A single block 1352 has two cylindrical bores. In the lower bore is a fixed sleeve 1354 which, in the vicinity of the passage 1350, has an external peripheral groove 1356. The groove, however, does not extend entirely around the sleeve but is stopped off at 1358 (Fig. 42), the safety line 1348 entering through the stopped-off portion to the inner side of the sleeve 1354. The line 1348 thus communicates initially with a peripheral groove 1360 in a timing piston 1362 which is bored nearly through lengthwise and contains a long compression spring 1364 one end of which is at the bottom of the bore and the other end of which is placed over a stud 1366 extending inwardly from a head 1368 secured to the block 1352, the head 1368 serving to limit leftward movement of the piston. The peripheral groove 1360 permits fluid to pass from the line 1348 along the groove to a

port 1370 leading to the passage 1350 and thence to the upper cylindrical bore in the block 1352. In this bore is a fixed sleeve 1372 partly lining the bore and in the part of the bore not occupied by the sleeve is a large piston 1374 connected by a neck 1376 to a small piston 1378 in the sleeve. This piston is connected by a neck 1380 to a second small piston 1382 also in the sleeve. The piston 1382 is connected to an arm 1384 which carries an indexing pin 1386. The pin is arranged to slide radially of the gear 62 and is impelled by a long compression spring 1388 to engage notches 1390 (Fig. 3) in an annular plate 1392 secured to the upper face of the gear 62. There are eight of the notches 1390 and adjacent to each notch is a cam surface 1394 partly formed in a removable plate 1396. After the pin 1386 has been withdrawn from one of the notches and the turret has started to rotate, the pin may be held by its spring 1388 against the cam surface which will control the radial movement of the pin until the next notch is reached, the pin then entering the notch.

Pressure fluid from the passage 1350 (Fig. 39) enters the space between the large piston 1374 and the small piston 1378 and, since the pressure on the large piston is greater than that on the small one, the pistons will move to the left against the spring 1388. A chamber 1398 is connected to an exhaust line 1400 (Fig. 3) from the indexing motor 74. When the pistons have moved to the left, a port 1402 (Fig. 39) in the sleeve 1372 is opened to allow fluid to pass around the neck 1380 through ports 1404 in the sleeve into a chamber 1406 which leads to the right-hand end of the piston 1362 which normally engages a projection 1410 on a head 1412 fastened to the block 1352. The piston 1362 will now be pushed to the left against the tension of the spring 1364 and the motor 74 will start indexing the turret. At the limit of its leftward movement, the right-hand end of the piston 1362 uncovers ports 1414 leading to a chamber 1416 connected to an exhaust pipe 1418. The motor will now be running at its highest speed which may be controlled by a globe valve 1420 in a pipe 1421 connecting the pressure line 1176 to the motor (Fig. 3). During the leftward movement of the piston 1362 the inlet of the pressure line 1348 and the port 1370 are closed by the full diameter portion of the piston and, when the piston reaches the limit of its movement, a peripheral groove 1422 therein overlies a port 1424 in the lower side of the sleeve 1354 and a port 1426 in the upper side of the sleeve which communicates with the exhaust chamber 1416. Thus, the pressure fluid which is holding the indexing pin withdrawn may pass along the groove 1356 in the sleeve on its unstoppered side to the port 1424 and by way of the groove 1422 in the piston to the port 1426 and to the exhaust pipe 1418. The spring 1388 will now force the indexing pin 1386 against the cam surface 1394, causing the right-hand end of the piston 1378 to close the port 1402, thus cutting down the amount of fluid being exhausted and hence the rate of the motor. Fluid can still pass, however, through a radial bore 1428 in the piston 1378 to an axial bore 1430 through the neck 1380 and part way through the piston 1382 to a port 1432 extending radially of the piston 1382 and at this time overlying a large port 1434 in the sleeve 1372. As the rotation of the turret continues, the cam surface 1394 will allow the pistons 1378 and 1382 to move farther toward the gear 62, thus gradually cutting off the passage of fluid from

the port 1402 to the radial passage 1428 and hence reducing the speed of the motor until the indexing pin drops into the next notch, whereupon the port 1432 will pass beyond the port 1434 and the motor will stop.

The action of the mechanism described for controlling the speed of the motor 74 by causing it to start slowly, run at high speed for a time and then slow down to a stop may be further enhanced by use of the mechanism disclosed in the patent to James No. 2,314,278 above referred to, which of itself, with the motor running at a uniform speed, will cause the turret to be started slowly, gradually speeded up to a maximum speed and gradually slowed down to zero speed at the conclusion of the indexing movement.

When the supply of pressure fluid to the piston 1362 is thus cut off, the spring 1364 will react to close the ports 1414. The only exit from the chamber 1406 is now through a pipe 1436 in the head 1412, flow through which is controlled by a needle valve 1438. As the piston 1362 is impelled by the spring 1364, it gradually forces the fluid trapped in the chamber 1406 through the needle valve until finally the groove 1360 uncovers the inlet opening of the pipe 1436, whereupon the turret may be again indexed. The valve therefore provides a timing device by which the rate of operation of the machine may be controlled.

As the turret starts to move (Figs. 3 and 45), the passage 1110 leading to the inflating device at the first station will move away from the pressure supplied through the port 1146 in the turret post and, there being no substantial loss of pressure in the cylinder 1106, the valve V-3 will remain raised. As the indexing movement of the turret is about to cease at station #2, the passage 1110 connects with the peripheral groove 1112 in the turret post which is constantly supplied with pressure fluid by the pump P-2 through port 1114 which is connected to the line 1115, pressure in which is regulated by the control valve C-3. Thus, inflating pressure in the pad 146 is maintained until station #8 is reached.

In the line 1176 connecting the valve V-10 and the valve V-4 there is preferably a dump valve 1440 (Fig. 46) consisting of a cylinder in which there is a spring-pressed piston 1442 movement of which by an angle lever 1444 opens the line 1176 to an exhaust pipe 1446. The angle lever is arranged with its operating arm 1447 in the path of the cams 1396 on the gear 62 so that early in the indexing movement of the turret the lever 1444 will be engaged by the cam and will move the piston 1442 against its spring to open the line 1176 to the exhaust 1446. This insures that the valve V-4 will be moved by its spring to exhaust position and that the fluid in the cylinder 1150 (M-11) will be exhausted to permit the valve V-3 to drop and dump the fluid in the cylinder 1106 of the inflating device.

When the turret has nearly completed its indexing movement, the cam 1276 trips the latches of valves V-12, V-14 and V-15, valve V-10 only remaining locked up (Fig. 43). The treadle C having been of course released, the valve V-12 moves down under its loading pressure, connecting line 1316 to exhaust. When the passage 1110 of the next inflating device comes opposite the turret port 146, there will be nothing to sustain pressure between the heads 1122, 1124 (Fig. 5) of the pad-inflating valve V-3 since the line 1316 is exhausted. The spring 1130, therefore, reacts to depress the valve and allow the pressure fluid in the inflating cylinder 1106 to flow

out. The tripping of valve V-14 closes the line 1101 from the wedge motor M-10 and connects the branch 1266 from the line 1020 with the line 1262 leading to the latch motor M-13 of valve V-10. The valve V-14 now connects the line 1268 from valve V-11 to exhaust, allowing valve V-11 to move down under its loading pressure to connect the pressure lines 1254, 1256 to line 1020, causing motor M-9 momentarily to operate to take the pressure off the wedges 1032, 1032' and control the reaction of the spring 1022. Since, during rotation of the turret, the dump valve 1440 is held open, valve V-4 will be held by its spring in exhaust position so that even if the momentary lifting of the plunger 1018 of motor M-9 supplies pressure to motor M-11 through line 1158 it will be exhausted through valve V-4 and will not operate motor M-11.

Pressure in the line 1020, however, will have passed via the line 1266, through valve V-14 to line 1262 of motor M-13 and tripped the latch of valve V-10, thus opening to exhaust the line 1100 to the wedge motor M-10 and allowing pressure in line 1198 to operate the wedge motor to pull the wedges out as well as to exhaust the pressure line 1020 of motor M-9.

Tripping of valve V-15 (Fig. 43) opens to exhaust line 1194 to valve V-5, causing the valve to drop and connect the pressure line 1178 with the line 518 to motors M-2, M-5 and M-3 so that when the lever 1298 is lifted by the cam 1300 on the next pad box as it goes into the first or operating station the latch 1293 will be released to permit motors M-2, M-3 and M-5 to move the forepart gages down over the pad and, since the pressure fluid in line 1338 drained off through valve V-13 when valve V-12 was tripped, valve V-1 will have been moved by its spring 114 to position to admit pressure from line 778 to motor M-7 to raise the support 730 of the rear gages.

The parts are now in position for a repetition of the operations described.

While the operation of the machine has been given, it will be convenient to provide a brief summary indicating the sequence and simultaneity of the acts of the operator, of the valves and of the motors. The electric motor M is started by operating a knob 1450 on the front of the machine (Fig. 1). The latch 1293 of the forepart gages has been released and the gages have been moved by the motors M-2, M-5 and M-6 into a position over the pad at the first station. The heel end gages have been moved up and over the heel end of the pad by the motor M-7. The forepart gages may be, for example, in position for operating on a right shoe, as shown in Fig. 43. If so, the operator will place a right sole O upon the pad against the sole toe gage 214 and operate the treadle A to move the wedge cam 218 which allows the motor M-1 to push the rod 204 upwardly to move the form 156 down and allow the forepart gages to engage and locate the forepart of the right sole.

The operator now depresses the valve V-2, permitting pressure fluid to pass from the line 902 through the port 894 to the upper end of the motor M-8 which operates the rack 864 to move the heel end gages toward each other to engage and locate the heel end of the sole. The operator now places a shoe S on the sole O with its toe end against the shoe toe gage 275 and allows the inclined surface 840 of the breast-line shoe gages to guide the shoe into the proper relation to the heel end of the sole. The operator

then, while holding the shoe with his right hand, grasps the handle 942 (Fig. 31) with his left hand, draws the bail 920 toward him until the finger 950 is just beyond the front cone C of the last and moves the handle 942 sidewise to locate the bearing member 946 over the rear cone of the last. The bail 910 thus released falls forward against the automatically positioned locating pin 954, thus locating the toe pad 912 properly lengthwise of the shoe. The mask plate 150 has also been positioned automatically lengthwise of the shoe in accordance with the length thereof.

The operator next depresses treadle B (Fig. 44) which opens valve V-6 and supplies pressure fluid from lines 1178, 1198 and 1252 to motors M-12, M-14 and M-15, and by the line 1264 to the motors thus causing valves V-10, V-14 and V-15 to be raised and latched up against the loading pressure supplied through line 1212 from the pump P-2 under control of the valve C-2. Pressure fluid from the pump P-1 through the line 1176 under control of the valve C-1 passes via the line 1254, through the valve V-10 and the valve V-11, via the line 1020 to the motor M-9 to operate the bails 910, 920. Raising of the valve V-10 caused fluid to pass through the check valve 1292 to the line 1100 to depress the piston of the motor M-10 and allow the springs 1070, 1072 to move the wedges in and thus maintain the pressure applied to the shoe by the motor M-9.

While the motor M-9 is operating, pressure fluid flows through the line 1170 to close the valve V-4 against the spring 1168. When the plunger of the motor M-9 reaches the limit of its movement, pressure fluid flows through the line 1158 to the motor M-11 to raise its piston and hold up the inflating valve V-3.

When the plunger of the wedge motor M-10 has been depressed to its limit, pressure fluid flows through line 1101, through the valve V-14 and the line 1268 to raise the valve V-11, thus cutting off the supply of pressure fluid to the motor M-9 and exhausting the line 1020, the wedges of course maintaining the pressure on the shoe. Simultaneously with the application of pressure to the shoe, fluid pressure passed through the valve V-10, the check valve 1292, the line 1100, the valve V-15 and the line 1194, to the valve V-5 which was thereby raised to cause the forepart gages to be retracted by the motors M-4 and M-6, this occurring after enough pressure has been applied to the shoe to prevent the shoe and sole from shifting relatively to each other.

Pressure fluid also passed from the pump P-1, through the valve V-5 to the line 906 leading to the top of the valve V-2 to depress it and thus cause pressure fluid to pass through the line 904 to the lower end of the motor M-8 which pushes up on the rack 864 and separates the heel end gages.

The operator now depresses the treadle C (Fig. 45), causing fluid pressure to flow to the motor M-16 of the valve V-12 to lift the valve. Since the valve V-11 is still held up by pressure fluid from line 1101 passing through the valve V-14 and the line 1268, the inlet from valve V-10 to valve V-11 is closed and the pressure in line 1254 builds up, lifting the control valve C-1 to open the line 1290 which, since the exhaust through the valve V-12 is now closed, flows through the line 1316 to the turret and thence through the open inflating valve V-3 to lift the piston 1108 of the inflating device and cause the pad to be

inflated. Pressure from the line 1316 flows also to valve V-13 and, when the bag pressure reaches a predetermined amount depending upon the loading of valve V-13 through the line 1232 by the pump P-2 and the pressure-control valve C-3, the valve V-13 opens, permitting fluid pressure to pass through the line 1338 to the valve V-4 which is opened to permit the fluid pressure in the motor M-7 to be exhausted and the heel end gages to swing away from the pad and descend out of the way of the turret. After the piston of motor M-7 has descended, fluid pressure in line 1338 flows through the peripheral grooves in the pistons of motors M-7, M-9, M-6 and M-4, provided these pistons are all in their required positions, and continues from the motor M-4 through the line 1348 to the timing valve TV, and, provided sufficient time has elapsed since the last indexing movement, through the timing valve by the passage 1350 to the motor M-17 which withdraws the indexing pin 1400 and opens the exhaust line 1368 of the fluid pressure indexing motor 74.

The pressure of the fluid in the exhaust line pushes on the cylinder 1362 (Fig. 39) of the timing valve TV until the ports 1414 are opened, thus allowing free exit to the exhaust from the motor 74 so that it can run at high speed. However, before the ports 1414 are opened, the pressure inlet 1348 to motor M-17 is closed by the cylinder 1362 and later, when the ports 1414 are opened, the passage 1350 is opened to the same exhaust through the port 1370, groove 1422, ports 1424, 1426 to the exhaust passage 1416. This de-energizes the motor M-17 and allows the spring 1388 to react to close the port 1402 and hold the indexing pin 1386 against its cam 1396 which, as the pin approaches the next indexing notch 1390, slows down the motor 74 by gradually closing the exhaust line 1400 to cut off the motor exhaust through port 1402, radial passage 1428 and axial passage 1430. In the meantime, the reaction of the spring 1364 has moved the piston 1362 far enough to close the ports 1414 and from then on the movement of the piston 1362 is controlled by the needle valve 1438 which is set to cause the required time to elapse, for example ten seconds, before, by movement of the piston, the groove 1360 connects the safety line 1348 to the port 1310 and to the passage 1350 again so that another indexing movement of the turret is possible.

Should the forepart gages, for example the ball gages 470, 472, fail properly to engage the edge face of the sole O, that is, should they close over the sole instead of against its edge face, it will be necessary to retract them. This is effected by a momentary push on the knob 1192 (Fig. 1) which lifts the valve V-5, as shown in Fig. 44. Pressure then flows from the pipe 1178 through the pipes 674, 530 and 672 to the motors M-4 and M-6 to retract the forepart gages. Should the valve V-5 be held up too long, the gages will be locked up by the latch 1292 and the front end of the lever 1298 must be lifted to release them. Moreover, if the gages are fully retracted, the plunger 582 will be operated to shift the position of the ball-line gages for the other sole of a pair. In that case, the knob 1192 is released to cause the gages to move in, or part way in, and is then pushed back to retract the gages again, whereupon the ball gages will be presented in their first position to correspond to the sole on the pad.

The pressure in the motor M-1 may prevent the treadle A from rising and thus prevent the form 156 from assuming its initial position. The

operator then momentarily moves the handle 1211 of valve V-9, as indicated by the arrow in Fig. 43, and then back again. This exhausts briefly the pressure on motor M-1 and allows the treadle A and wedge cam 218 to assume their initial positions. He can then operate the treadle A to cause movement of the form as before.

It may happen, after treadle B has been depressed to apply pressure to the shoe, that the shoe and sole are not properly positioned or that the shoe is tipped and does not occupy its proper relation to the pad. To correct such difficulties it is necessary to release the pressure on the shoe. This is done by pulling on the handle 1280 (Fig. 43) to release the latches 1270, 1271 of valves V-14 and V-15, whereupon pressure in line 1266 will pass through valve V-14 to motor M-13 and trip the latch of valve V-10, thus restoring the parts to the positions they were in before treadle B was depressed, pressure on the shoe being thus relieved. The restoration of the gages to proper position for the shoe in hand may be effected as above indicated.

Having thus described my invention, what I claim as new and desire to secure by Letters Patent of the United States is:

1. In a cement sole-attaching machine, a pad, means for locating a sole on the pad, a form for determining the position of said locating means on the pad, and means for applying pressure to a shoe placed on the sole.

2. In a cement sole-attaching machine, a pad, ball gages for locating a sole on the pad, fluid-pressure-operated means for moving the gages toward each other, a form for controlling such movement of said gages, and means for applying pressure to a shoe placed on the sole.

3. In a cement sole-attaching machine, a pad, means for locating a sole on the pad, a duplex form for determining the position of said locating means on the pad for either a right or a left shoe, and means for applying pressure to a shoe placed on the sole.

4. In a cement sole-attaching machine, a pad, means for locating the forepart of a sole on the pad, a form resembling a pair of truncated cones with their bases facing each other for determining the position of said locating means on the pad, movement of the form along a line perpendicular to said bases in one direction causing operation of the gages to locate a sole for one foot and movement of the form in the opposite direction causing movement of the gages to locate a sole for the other foot, and means for applying pressure to a shoe placed on the sole.

5. In a cement sole-attaching machine, a pad to receive a sole, gages for locating the sole with the longitudinal median line of its shank portion parallel to the longitudinal center line of the pad, and a form for determining the position of said gages for either a right or a left sole.

6. In a cement sole-attaching machine, a pad to receive a sole, gages for locating the sole with the heel end centrally of the pad, gages for locating the forepart of the sole with the longitudinal median line of its forepart at such an angle that the longitudinal median line of the shank part is parallel to the longitudinal axis of the pad, and a form for determining the position of said forepart gages.

7. In a cement sole-attaching machine, a pad to receive a sole, gages for locating a sole in which the longitudinal median line of its shank portion makes a predetermined angle with the longitudinal median line of the forepart so that the lon-

longitudinal median line of the rear part will be parallel to the longitudinal center line of the pad, and a form for determining the position of said gages.

8. In a cement sole-attaching machine, a pad to receive a sole, heel end gages for locating the breast line of the sole centrally of the rear part of the pad, forepart gages for locating the forepart of the sole so that the longitudinal median line of its shank portion will be parallel to the longitudinal center line of the pad, and a form for controlling the closing of said forepart gages on the forepart of the sole.

9. In a cement sole-attaching machine, a pad to receive a sole, gages for locating the forepart of the sole in a predetermined position on the forepart of the pad, and a form controlling movement of said gages so as to locate any sole of a run of sizes with its ball line in predetermined relation to the pad.

10. In a cement sole-attaching machine, a pad to receive a sole, gages for locating the forepart of the sole on the forepart of the pad, and a form controlling movement of said gages so as to locate any sole of a run of sizes with the longitudinal median line of the rear part in predetermined relation to the pad.

11. In a cement sole-attaching machine, a pad to receive a sole, gages for locating the forepart of the sole in a predetermined position on the forepart of the pad, and a right and left form controlling movement of said gages so as to locate any sole of a run of sizes of either rights or lefts with its ball line in predetermined relation to the pad.

12. In a cement sole-attaching machine, a pad to receive a sole, a sole toe gage engaging opposite sides of the toe end of the sole and gages for engaging the sole at the ends of the ball line for locating the forepart of the sole in a predetermined position on the forepart of the pad, and means for automatically controlling movement of said gages to locate any sole of a run of sizes with its ball line located centrally of the pad and with the longitudinal median line of its rear part coincident with the longitudinal median line of the pad.

13. In a cement sole-attaching machine, a plurality of pads for right and left shoes, a single set of gages movable into and out of position to locate soles on either pad, and means controlled by movement of the gages for shifting the gages for operation on right and left soles.

14. In a cement sole-attaching machine, a plurality of pads for right and left shoes, toe-end and ball-line gages movable into and out of position to locate a sole on either pad, and means controlled by said movement of the gages for shifting the ball-line gages for operation alternately on right and left soles.

15. In a cement sole-attaching machine, a plurality of pads for right and left shoes, a single set of gages movable into and out of position to locate soles on either pad, and means operated by movement of the gages for shifting the gages from position for operation on a right sole into position for operating on a left sole and vice versa.

16. In a cement sole-attaching machine, a plurality of pads for right and left shoes, a gage carrier, a single set of gages on said carrier movable by the carrier into and out of position over the pads to locate a sole on either pad, and means controlled by movement of the gage carrier for shifting the gages for operation first on a right and then on a left sole.

17. In a machine for operating alternately on right and left shoes, gages for locating a sole, and a form movable in one direction for controlling the gages for locating a sole for one foot and movable in another direction to control movement of the gages for locating a sole for the other foot.

18. In a machine for operating alternately on right and left shoes, gages for locating a sole, and a duplex form movable heightwise of the sole in one direction for controlling the gages for locating a sole for one foot and movable heightwise of the sole in the other direction to control movement of the gages for locating a sole for the other foot.

19. In a machine for operating alternately on right and left shoes, gages for locating the forepart of a sole, and a form movable in one direction for controlling movement of the gages for locating any sole of a series of sizes for one foot and movable in the opposite direction to control movement of the gages for locating any sole of a series of sizes for the other foot.

20. In a machine for operating alternately on right and left shoes, gages for locating the forepart of the sole on the forepart of the pad, and a form controlling movement of said gages so as to locate any sole of a run of sizes with the longitudinal median line of the rear part in predetermined relation to the pad.

21. In a machine for operating alternately on right and left soles, a support for the sole, gages for locating the forepart of a sole on the support, a form movable in one direction for controlling the gages for locating the sole of a shoe for one foot and movable in the opposite direction for controlling the gages for locating the sole of a shoe for the other foot, fluid-pressure-operated means constructed and arranged to move the form first in one direction and then in the other, and manually operated means for controlling the fluid-pressure-operated means.

22. In a cement sole-attaching machine, a pad, gages for alternately locating right and left soles on the pad, a form movable in one direction for controlling the gages for locating the sole of a shoe for one foot and movable in the opposite direction for controlling the gages for locating a sole of a shoe for the other foot, means for moving the form in either direction, and manually operated means operable in the same direction for controlling the movement of the form first in one direction and then in the other.

23. In a machine for pressing soles on shoes, a pad, gages for operating alternately on right and left soles, a form movable in one direction for controlling the gages to locate the sole of a shoe for one foot and movable in the opposite direction for controlling the gages to locate the sole of a shoe for the other foot, fluid-pressure-operated means for automatically moving the form first in one direction and then in the other, and manually operated means operable always in the same direction for controlling the movement of the form first in one direction and then in the other.

24. In a shoe machine, a series of sole supports arranged to receive right and left soles in alternation, a single set of gages for locating soles on the supports in succession, a form movable in one direction for controlling the gages to locate the sole of a shoe for one foot and movable in the opposite direction for controlling the gages to locate the sole of a shoe for the other foot, and fluid-pressure-operated means for moving the

form first in one direction and then in the other.

25. In a machine for operating alternately on right and left shoes, gages for locating a shoe sole, a form movable in one direction for controlling the gages for locating the sole of a shoe for one foot and movable in another direction to control movement of the gages for locating the sole of a shoe for the other foot, and fluid-pressure-operated means for moving the form first in one direction for a right sole and then in the other direction for a left sole.

26. In a machine for operating alternately on right and left shoes, gages for locating a shoe sole, a form movable in one direction for controlling the gages for one sole and movable in another direction to control movement of the gages for a sole for the other foot, fluid-pressure-operated means for moving the form first in one direction for a right sole and then in the other direction for a left sole, and manually operated means for controlling operation of said fluid-pressure-operated means.

27. In a machine for operating alternately on right and left shoes, a series of right and left pads alternately arranged, gages for locating a shoe sole on any one of the pads, a form movable in one direction for controlling the gages for locating a right sole and movable in another direction to control movement of the gages for locating a left sole, and fluid-pressure-operated means under control of the operator for moving the form first in one direction for a right sole and then in the other direction for a left sole.

28. In a machine for operating alternately on right and left shoes, a plurality of pads, means for presenting the pads in turn at an operating station, a single set of gages for locating a shoe sole on each pad in turn, a form movable in one direction for controlling the gages for locating the sole of a shoe for one foot and movable in another direction to control movement of the gages for the sole of a shoe for the other foot, and fluid-pressure-operated means for moving the form first in one direction for a right sole and then in the other direction for a left sole.

29. In a machine for attaching soles to shoes, a series of right and left pads arranged alternately, means for moving the pads to present them in turn at an operating station, gages movable into and out of operative position over the pads in turn, and means for alternately setting the gages in accordance with the right and left characteristics of the pads.

30. In a machine for attaching soles to shoes, a series of right and left pads arranged alternately, means for presenting the pads in turn at an operating station, a pair of ball line gages movable at the operating station into and out of operative position over the pads for engaging a sole adjacent to the ends of the ball line, and means for alternately setting the gages for locating right and left soles.

31. In a machine for attaching soles to shoes, a series of right and left pads arranged alternately, means for presenting the pads in turn at an operating station, gages at the operating station movable into and out of operative position over the pads, and means operated by the movement of the gages for alternately setting the gages in accordance with right and left characteristics of the pads.

32. In a machine for attaching soles to shoes, a series of right and left pads arranged alternately, means for presenting the pads in turn at an operating station, gages movable into and out

5 of operative position over each pad as it is presented at the operating station, fluid-pressure-operated mean for moving the gages into and out of operative position over the pad, and means operated by movement of the gages out of operative position for alternately setting the gages in accordance with right and left characteristics of the pads.

10 33. In a machine for applying pressure to shoes, a pad, means for locating a shoe on the pad, a form for determining the position of said locating means on the pad, and means for applying pressure to the shoe.

15 34. In a machine for applying pressure to shoes, a pad, means for locating a shoe on the pad, a duplex form for determining the position of said locating means on the pad for either a right or a left shoe, and means for applying pressure to the shoe.

20 35. In a machine for applying pressure to shoes, a pad, means for locating the forepart of a shoe on the pad, a form resembling a pair of truncated cones with their bases facing each other for determining the position of said locating means on the pad, movement of the form along a line perpendicular to said bases in one direction causing operation of the gages to locate a shoe for one foot and movement of the form in the opposite direction causing movement of the gages to locate a shoe for the other foot, and means for applying pressure to the shoe.

25 36. In a machine for applying pressure to shoes, a pad to receive a shoe, toe-end and breast-line gages for locating the shoe with the longitudinal median line of its shank portion parallel to the longitudinal center line of the pad, a form for determining the position of said toe-end gages for either a right or a left shoe, and means for pressing the shoe on the pad.

30 37. In a machine for applying pressure to shoes, a pad to receive a shoe, gages for locating the shoe with the heel end centrally of the pad, gages for locating the forepart of the shoe with the longitudinal median line of its forepart at such an angle that the longitudinal median line of the shank part is parallel to the longitudinal axis of the pad, a form for determining the position of said forepart gages, and means for applying pressure to the shoe.

35 38. In a machine for applying pressure to shoes, a pad to receive a shoe, gages for locating a shoe in which the longitudinal median line of its shank portion makes a predetermined angle with the longitudinal median line of the forepart so that the longitudinal median line of the rear part will be parallel to the longitudinal center line of the pad, a form for determining the position of said gages, and means for applying pressure to the shoe.

40 39. In a machine for applying pressure to shoes, a pad to receive a shoe, heel end gages for locating the breast line of the shoe centrally of the rear part of the pad, toe-end gages for locating the toe of the shoe so that the longitudinal median line of its shank portion will be parallel to the longitudinal center line of the pad, a form for controlling the position and movement of said toe-end gages, and means for applying pressure to the shoe.

45 40. In a machine for applying pressure to shoes, a pad to receive a shoe, gages for locating the toe end of the shoe in a predetermined position on the forepart of the pad, a form controlling movement of said gages so as to locate 70 any shoe of a run of sizes with its ball line in

predetermined relation to the pad, and means for applying pressure to the shoe.

41. In a machine for applying pressure to shoes, a pad to receive a shoe, gages for locating the forepart of the shoe on the forepart of the pad, a form controlling movement of said gages so as to locate any shoe of a run of sizes with the longitudinal median line of the rear part of the shoe in central position relatively to the rear part of the pad, and means for applying pressure to the shoe.

42. In a machine for applying pressure to shoes, a pad to receive a sole, gages for locating the forepart of the shoe in a predetermined position on the forepart of the pad, a right and left form controlling movement of said gages so as to locate any sole of a run of sizes of either rights or lefts with its ball line in substantially the same position longitudinally of the pad, and means for applying pressure to the shoe.

43. In a machine for applying pressure to shoes, a pad to receive a shoe, a shoe toe gage engaging opposite sides of the toe end of the sole, gages for engaging the shoe at the ends of the breast line, a form controlling movement of said toe gage to locate any shoe of a run of sizes with its ball line located centrally longitudinally of the pad and with the longitudinal median line of its rear part coincident with the longitudinal median line of the pad, and means for applying pressure to the shoe.

44. In a machine for applying pressure to shoes, a plurality of pads alternately for right and left shoes, a single set of gages movable into and out of position to locate shoes on the pads in succession, and means controlled by movement of the gages out of operative position for shifting the gages for operation alternately on right and left shoes.

45. In a machine for applying pressure to shoes, a plurality of pads for right and left shoes, a single set of gages movable into and out of position to locate shoes on either pad, and means operated by movement of the gages for shifting the gages from position for operation on a right shoe into position for operating on a left shoe and vice versa.

46. In a cement sole-attaching machine, a plurality of pads for right and left shoes, a gage carrier, a single set of shoe toe gages on said carrier movable by the carrier into and out of position over the pads to locate a sole on either pad, and means controlled by movement of the gage carrier for shifting the shoe toe gages for operation first on a right and then on a left sole.

47. In a machine for operating alternately on right and left shoes, gages for locating a shoe, and a form movable in one direction for controlling the gages for locating a shoe for one foot and movable in another direction to control movement of the gages for locating a shoe for the other foot.

48. In a machine for operating alternately on right and left shoes, gages for locating a shoe, and a duplex form movable heightwise of the sole in one direction for controlling the gages for locating a shoe for one foot and movable heightwise of the sole in the other direction to control movement of the gages for locating a shoe for the other foot.

49. In a machine for operating alternately on right and left shoes, gages for locating the forepart of a shoe, and a form movable in one direction for controlling movement of the gages for locating any shoe of a series of sizes for one foot

and movable in the opposite direction to control movement of the gages for locating any shoe of a series of sizes for the other foot.

50. In a machine for operating alternately on right and left shoes, gages for locating a shoe, a form movable in one direction for controlling the gages for locating shoes for one foot and movable in another direction to control movement of the gages for locating shoes for the other foot, and fluid-pressure-operated means for moving the form in either direction.

51. In a machine for operating alternately on right and left soles, a support for the sole, gages for locating the forepart of a shoe on the support, a form movable in one direction for controlling the gages for locating a shoe for one foot and movable in the opposite direction for controlling the gages for locating a shoe for the other foot, fluid-pressure-operated means constructed and arranged to move the form first in one direction and then in the other, and manually operated means for controlling the fluid-pressure-operated means.

52. In a cement sole-attaching machine, a pad, gages for alternately locating right and left shoes on the pad, a form movable in one direction for controlling the gages for locating a shoe for one foot and movable in the opposite direction for controlling the gages for locating a shoe for the other foot, means for moving the form in either direction, and manually operated means operable in the same direction for controlling the movement of the form first in one direction and then in the other.

53. In a machine for pressing soles on shoes, a pad, gages for operating alternately on right and left shoes, a form movable in one direction for controlling the gages to locate a shoe for one foot and movable in the opposite direction for controlling the gages to locate a shoe for the other foot, fluid-pressure-operated means for automatically moving the form first in one direction and then in the other, and manually operated means operable always in the same direction for controlling the movement of the form first in one direction and then in the other.

54. In a shoe machine, a series of sole supports arranged to receive right and left shoes in alternation, a single set of gages for locating shoes on the supports in succession, a form movable in one direction for controlling the gages to locate a shoe for one foot and movable in the opposite direction for controlling the gages to locate a shoe for the other foot, and fluid-pressure-operated means for moving the form first in one direction and then in the other.

55. In a machine for operating alternately on right and left shoes, gages for locating a shoe, a form movable in one direction for controlling the gages for locating a shoe for one foot and movable in another direction to control movement of the gages for locating a shoe for the other foot, and fluid-pressure-operated means for moving the form first in one direction for a right sole and then in the other direction for a left sole.

56. In a machine for operating alternately on right and left shoes, gages for locating a shoe, a form movable in one direction for controlling the gages for one shoe and movable in another direction to control movement of the gages for a shoe for the other foot, fluid-pressure-operated means for moving the form first in one direction for a right shoe and then in the other direction for a left shoe, and manually operated means for

controlling operation of said fluid-pressure-operated means.

57. In a machine for operating alternately on right and left shoes, a series of right and left pads alternately arranged, gages for locating a shoe on any one of the pads, a form movable in one direction for controlling the gages for locating a right shoe and movable in another direction to control movement of the gages for locating a left shoe, and fluid-pressure-operated means under control of the operator for moving the form first in one direction for a right shoe and then in the other direction for a left shoe.

58. In a machine for operating alternately on right and left shoes, a plurality of pads, means for presenting the pads in turn at an operating station, a single set of gages for locating a shoe on each pad in turn, a form movable in one direction for controlling the gages for locating a shoe for one foot and movable in another direction to control movement of the gages for a shoe for the other foot, and fluid-pressure-operated means for moving the form first in one direction for a right shoe and then in the other direction for a left shoe.

59. In a machine for applying pressure to shoe bottoms, a pad, means for applying pressure to the shoe to press it upon the pad comprising an abutment movable longitudinally of the shoe to locate it with respect to the forepart thereof, and means independent of the shoe for automatically locating said forepart abutment longitudinally of the shoe in accordance with the length thereof.

60. In a machine for applying pressure to shoe bottoms, a pad, means for applying pressure to the shoe to press it upon the pad comprising an abutment movable longitudinally of the shoe to locate it with respect to the forepart thereof, a form, and means controlled by the form for locating the forepart abutment longitudinally of the shoe in accordance with the length thereof.

61. In a machine for applying pressure to shoe bottoms, a pad, means for applying pressure to the shoe to press it upon the pad comprising an abutment movable longitudinally of the shoe to locate it with respect to the forepart thereof, means for automatically locating the forepart abutment longitudinally of the shoe in accordance with the length thereof, and means for varying the position automatically assumed by said abutment.

62. In a machine for applying pressure to shoe bottoms, a pad, means for applying pressure to the shoe to press it upon the pad comprising an abutment movable longitudinally of the shoe to locate it with respect to the forepart thereof, a form, means controlled by the form for locating the forepart abutment longitudinally of the shoe in accordance with the length thereof, and means under control of the operator for varying the position in which the abutment is located by said form.

63. In a machine for applying pressure to shoe bottoms, an inflatable pad, a mask plate on the pad for controlling the distortion of the pad, said mask plate being movable longitudinally of the pad, a form, and connections between the form and said mask plate to cause the mask plate to be positioned in accordance with the size of a sole located on the pad.

64. In a machine for applying pressure to shoe bottoms, an inflatable pad, a mask plate on the pad for controlling the distortion of the pad, said mask plate being movable longitudinally of the pad in the direction of the longitudinal

median line of the forepart of a sole placed on the pad, a form, and connections between the form and said mask plate to cause the mask plate to be positioned in accordance with the size of a sole located on the pad.

5 65. In a machine for applying pressure to shoe bottoms, a yielding pad, a mask plate on the pad for controlling the distortion of the pad, said mask plate being movable longitudinally of the pad, a spring normally holding the mask plate in retracted position, a carriage movable longitudinally of the pad, a form arranged to arrest movement of the carriage toward the heel end of the pad, and means on the carriage to engage the mask plate and move it toward the rear end of the pad to an extent controlled by said form.

10 66. In a machine for applying pressure to shoe bottoms, a yielding pad, a mask plate located beneath the pad, said mask plate being mounted for movement longitudinally of the pad, automatic means for locating the mask plate longitudinally of the pad in accordance with the size of the shoe being operated upon, and means for varying the position so assumed by the mask plate.

15 67. In a machine for applying pressure to shoe bottoms, a yielding pad comprising upper and lower layers, a mask plate located between the layers of the pad for controlling distortion thereof, said mask plate being mounted for movement longitudinally of the pad, means for automatically locating the mask plate longitudinally of the pad in accordance with the size of the shoe being operated upon, and operator-controlled means for varying the position automatically assumed by the mask plate.

20 68. In a machine for attaching soles to shoes, a series of right and left pads arranged alternately, means for presenting the pads in turn at an operating station, shoe and sole gages at the operating station movable into and out of operative position over the pads, said gages being shiftable to adapt them for relatively locating right and left shoes and soles, and means operated by the movement of the gages for alternately setting the gages in accordance with the right and left characteristics of the shoes and soles.

25 69. In a machine for attaching soles to shoes, a series of right and left pads arranged alternately, means for presenting the pads in turn at an operating station, shoe and sole gages movable into and out of operating position over the forepart of each pad as it is presented at the operating station, said gages being shiftable for relatively locating either right or left shoes and soles, means for moving the gages into and out of operative position over the pad, and means operated by movement of the gages out of operative position for shifting the gages.

30 70. In a machine for attaching soles to shoes, a series of right and left pads arranged alternately, means for moving the pads to present them in turn at an operating station, shoe and sole gages movable into and out of operative position over the forepart and the heel end of the pads in turn, and means for alternately setting the gages on the forepart pad in accordance with right and left characteristics of the shoe and sole.

35 71. In a machine for attaching soles to shoes, a series of right and left pads arranged alternately, means for presenting the pads in turn at an operating station, a pair of ball-line sole gages movable at the operating station into and out of operating position over the pads for engaging a sole adjacent to the ends of the ball line, gages for locating the toe end of the shoe and sole also

movable into and out of position over the pads, and means for alternately setting the gages for locating right and left soles and shoes relatively to each other.

72. In a machine for applying pressure to shoe bottoms, a pad comprising a solid layer and an inflatable layer, a mask plate located between the layers for controlling the distortion of the pad, and means for automatically shifting the mask plate longitudinally of the pad in accordance with the size of the sole presented on the pad.

73. In a machine for applying pressure to shoe bottoms, a pad comprising a solid layer and an inflatable layer, a mask plate located between the layers for controlling the distortion of the pad, means for automatically shifting the mask plate longitudinally of the pad in accordance with the size of the sole presented on the pad, and means for varying the position automatically assumed by the mask plate.

74. In a machine for applying pressure to shoe bottoms, a yielding pad, a mask plate for controlling distortion of the pad, a form, and means controlled by the form for locating the mask plate longitudinally of the pad in accordance with the size of the sole presented on the pad.

75. In a machine for applying pressure to shoe bottoms, a pad comprising a solid layer and an inflatable layer, a mask plate located between the layers for controlling the distortion of the pad, and a form for automatically shifting the mask plate in accordance with the size of the sole presented on the pad.

76. In a machine for cement-attaching soles to shoes, the combination of a pad comprising a solid layer and an inflatable layer, a carriage movable longitudinally of the pad, a gage on said carriage to engage the toe of a sole placed on the pad, a mask plate movable lengthwise of the pad between the layers of the pad, and connections between said mask plate and the carriage to cause the mask plate to be located longitudinally in accordance with the position of said toe gage.

77. In a machine for cement-attaching soles to shoes, the combination of a pad, a carriage movable longitudinally of the pad, a gage on said carriage to engage the toe of a sole placed on the pad, a form for controlling the position of said toe gage, a mask plate movable lengthwise of the pad, and connections between said mask plate and the carriage to cause the mask plate to be located longitudinally in accordance with the position of said toe gage.

78. In a machine for cement-attaching soles to shoes, a pad, a carrier movable longitudinally and laterally of the pad, a gage on said carriage to engage the toe of a sole placed on the pad, a mask plate movable lengthwise of the pad, bars mounted for movement longitudinally of the pad in position to engage the mask plate, and means on the carriage to engage the bars and move them longitudinally to an extent determined by the position of said toe gage.

79. In a machine for cement-attaching soles to shoes, a pad, a carrier movable longitudinally and laterally of the pad, a gage on said carriage to engage the toe of a sole placed on the pad, a form for controlling the position of said toe gage longitudinally of the pad, a mask plate movable lengthwise of the pad, bars mounted for movement longitudinally of the pad in position to engage the mask plate, and means on the carriage to engage the bars and move them longitudinally to an extent determined by the position of said toe gage.

80. In a machine for cement-attaching soles to shoes, a pad, a carriage movable longitudinally and laterally of the pad, a gage on said carriage to engage the toe of a sole placed on the pad, a form for controlling the lateral and longitudinal position of said toe gage, a mask plate movable lengthwise of the pad, means movable longitudinally only of the pad to engage the mask plate and move it longitudinally of the pad, and a shiftable stop on the carriage to engage said means and move the mask plate to an extent determined by the position of said toe gage.

81. In a cement sole-attaching machine, the combination of a pad, means for pressing a shoe on the pad, parallel bars mounted for longitudinal sliding movement and for movement in parallelism toward and from each other, stops for limiting movement of the bars over the pad, sole ball gages on the bars, means for alternately shifting the stops to cause the gages to be located opposite the ends of the ball line of a right shoe and then opposite the ball line of a left shoe, and means for moving the bars toward each other to cause the gages to engage the sole.

82. In a cement sole-attaching machine, a pad, means for pressing a shoe on the pad, parallel bars mounted for longitudinal sliding movement into and out of position over the pad, fluid-pressure-operated means for moving the bars, stops for limiting movement of the bars over the pad, sole ball gages on the bars, and means operated by said fluid-pressure-operated means for alternately shifting the stops to cause the gages to be located opposite the ends of the ball line of a right shoe and then opposite the ends of the ball line of a left shoe.

83. In a cement sole-attaching machine, a pad, means for pressing a shoe on the pad, a carriage mounted for movement longitudinally of the pad, parallel bars mounted for longitudinal sliding movement, stops for limiting movement of the bars over the pad, sole ball gages on said bars, a gage on said carriage to engage the toe end of the sole, means controlling movement of said gage so that a sole of any size will be located with its ball in predetermined position on the pad, and means for alternately shifting the stops to cause the gages to be located opposite the ends of the ball line of a right sole and then opposite the ball line of a left sole.

84. In a cement sole-attaching machine, the combination of a pad, parallel bars mounted for movement longitudinally of the pad, a ball-line sole gage carried by each bar, means for moving the bars toward each other and maintaining them in parallelism, and means for stopping the bars in positions such that one gage will be up and the other down alternately.

85. In a cement sole-attaching machine, a pad, parallel bars mounted for movement longitudinally of the pad, a ball-line sole gage carried by each bar, means for moving the bars toward each other and maintaining them in parallelism, and means for shifting the bars longitudinally the one up and the other down alternately to locate the ball-line sole gages opposite the ends of the ball lines of right and left soles.

86. In a cement sole-attaching machine, a pad, a sole toe gage movable laterally and longitudinally of the pad, and a form arranged to control the position of the toe gage so that a sole irrespectively of its size will be located with the center of its ball line in predetermined position longitudinally of the pad.

87. In a cement sole-attaching machine, a pad,

means for pressing a shoe on the pad, a carriage mounted for movement longitudinally of the pad, parallel bars mounted for longitudinal sliding movement, stops for limiting movement of the bars over the pad, sole ball-line gages on said bars, a gage on said carriage to engage the toe of the sole, means controlling movement of said gage so that a sole of any size will be located with its ball in predetermined position on the pad, means for alternately shifting the stops to cause the sole ball-line gages to be located opposite the ends of the ball line of a right sole and then opposite the ends of the ball line of a left sole, and means for moving the sole ball-line gages toward each other to engage the sole.

88. In a cement sole-attaching machine, a form having inclined surfaces the distance apart of which corresponds to the length of the ball lines of a series of shoe sizes, form ball-line gages arranged to engage said surfaces, a first pair of parallel bars carrying said gages, means for moving the bars toward each other to engage said surfaces, means for maintaining the parallelism of the bars as they are moved, stops carried by said bars, a second pair of parallel bars connected with the first pair of parallel bars for movement in parallelism therewith and for movement longitudinally, sole ball-line gages on said second parallel bars, and abutments on said second parallel bars to engage the stops on the first parallel bars to cause the sole ball-line gages to be located in accordance with the position assumed by the form ball-line gages upon contact with the form.

89. In a cement sole-attaching machine, the combination of a form having inclined surfaces the distance apart of which corresponds to the length of the ball lines of a series of sole sizes, form ball-line gages arranged to engage said surfaces, sole ball-line gages, and mechanism connecting said form ball-line gages and said sole ball-line gages to cause the sole ball-line gages to be moved in accordance with the position of the form ball-line gages as determined by their contact with the form.

90. In a cement sole-attaching machine, the combination of a form having inclined surfaces the distance apart of which corresponds to the length of the ball line of a series of sole sizes, form ball-line gages arranged to engage said surfaces, sole ball-line gages, and parallel bars connecting said form ball-line gages and said sole ball-line gages to cause the sole ball-line gages to be moved in accordance with the position of the form ball-line gages as determined by their contact with the form.

91. In a cement sole-attaching machine, the combination of a form having inclined surfaces the distance apart of which corresponds to the length of the ball line of a series of sole sizes, form ball-line gages arranged to engage said surfaces, sole ball-line gages, and mechanism comprising a pair of bars mounted for longitudinal movement and for movement toward and from each other in parallelism on which said gages are mounted.

92. In a cement sole-attaching machine, the combination of a form having inclined surfaces the distance apart of which corresponds to the length of the ball line of a series of sole sizes, form ball-line gages arranged to engage said surfaces, sole ball-line gages, mechanism comprising two pairs of parallel bars, a first pair carrying the form ball-line gages and a second pair the sole ball-line gages, and means for imparting to the

second pair movement to locate the sole ball-line gages upon the pad in positions corresponding to the positions of the first pair of bars as determined by the form.

93. In a cement sole-attaching machine, a form having inclined surfaces the distance apart of which corresponds to the length of the ball lines of a series of shoe sizes, form ball-line gages arranged to engage said surfaces, a first pair of parallel bars movable longitudinally and carrying said gages, means for moving the bars toward each other to engage said surfaces, means for setting the one bar up and the other down to position the form ball-line gages for engagement with the inclined surfaces of the form, means for maintaining the parallelism of the bars as they are moved, stops carried by said bars, a second pair of parallel bars connected with the first pair of parallel bars for movement in parallelism therewith and for movement longitudinally, sole ball-line gages on said second parallel bars, and abutments on said second parallel bars to engage the stops on the first parallel bars to cause the sole ball-line gages to be located in accordance with the position assumed by the form ball-line gages upon contact with the form.

94. In a cement sole-attaching machine, a duplex form having on one side inclined surfaces the distance apart of which corresponds to the length and direction of the ball lines of a series of right shoe sizes and on the other side inclined surfaces the distance apart of which corresponds to the length and direction of the ball lines of a series of left shoe sizes, form ball-line gages arranged to engage said surfaces, a first pair of parallel bars carrying said gages, means for moving the bars toward each other and longitudinally to engage the inclined surfaces on the right form, means for maintaining the parallelism of the bars as they are moved, stops carried by said bars, a second pair of parallel bars connected with the first pair of parallel bars for movement in parallelism therewith and for movement longitudinally, sole ball-line gages on said second parallel bars, abutments on said second parallel bars to engage the stops on the first parallel bars to cause the sole ball-line gages to be located longitudinally of the pad in accordance with the position assumed by the form ball-line gages upon contact with the right form, and means for shifting the first pair of parallel bars the one up and the other down to cause the form ball-line gages carried thereby to be positioned to engage the inclined surface of the left-hand form whereupon the form ball-line gages will be located to engage the inclined surfaces of the left-hand form and the stops will be located to position the sole ball-line gages for operation on a left sole.

95. In a cement sole-attaching machine, a carrier rotatable about a vertical axis, a plurality of pads on the carrier to be presented in turn at an operating station by rotation of the carrier, means for applying pressure to a shoe on the pad at the operating station, pawl-and-ratchet means for maintaining the pressure on the shoe after the pressure-applying means has ceased to act, and wedge means for taking up any space between the pawl and a tooth of the ratchet.

96. In a machine for applying pressure to shoe bottoms, a pad to receive a shoe, means for applying pressure to the shoe, a toothed strut carried by said pressure-applying means, a pawl arranged to engage the teeth of the strut, and a wedge movable to take up any space between the teeth of the strut and the pawl positively to maintain

said pressure-applying means in pressure-applying position.

97. In a machine for applying pressure to shoe bottoms, a pad box, a pad in the box to receive a shoe, means for applying pressure to the shoe, an outer sleeve carried by the box, an inner sleeve in said outer sleeve, a wedge between said sleeves acting to move the sleeves relatively to each other, a toothed strut carried by the pressure-applying means and housed in the inner sleeve, a pawl carried by the inner sleeve and arranged to engage the teeth on the strut, and means for moving the wedge to cause the pawl to move into engagement with an adjacent tooth and maintain all the pressure applied by said pressure-applying means.

98. In a machine for applying pressure to shoe bottoms, a pad box, a pad in the box to receive a shoe, means for applying pressure to the shoe, an outer sleeve carried by the box, an inner sleeve in said outer sleeve, a wedge between said sleeves acting to move the sleeves relatively to each other, a toothed strut carried by the pressure-applying means and housed in the inner sleeve, a pawl carried by the inner sleeve and arranged to engage the teeth on the strut, a spring urging the pawl toward tooth-engaging position, means operated by withdrawal of the wedge for holding the pawl out of tooth-engaging position, and means for moving the wedge to release the pawl and move it into engagement with an adjacent tooth thereby maintaining all the pressure applied by said pressure-applying means.

99. A sole-locating gage comprising a series of oblong wire loops having straight ends arranged directly to engage the edge face of the sole, said ends being arranged obliquely to the plane of the sole to cause the loops to tip in response to heightwise pressure, and means for restoring the loops to initial position.

100. A gage for sole-attaching machines comprising separated plates, and a series of wire loops between the plates, said loops being constructed and arranged to provide a gage surface for the edge face of the sole and said loops being inclined to the planes of the plates so that when the plates are pressed toward each other the loops will slip sidewise while maintaining their locating function on the pad.

101. A gage for sole-attaching machines comprising separated plates, a series of wire loops between the plates, said loops being constructed and arranged to provide a gage surface for the edge face of the sole and said loops being inclined to the planes of the plates so that when the plates are pressed toward each other the loops will slip sidewise while maintaining their locating function on the pad, and means for restoring the loops to initial position when the plates are separated.

102. A gage for locating soles comprising three plates, spring wire loops located between two of the plates with the plane of the loops inclined to the plane of the plates, said loops having portions at right angles to the plates to engage the sole edge, and lateral arms engaging one of the plates to hold the loops in initial position.

103. A gage for locating soles comprising three plates, spring wire loops located between two of the plates with the plane of the loops inclined to the plane of the plates, said loops having portions at right angles to the plates to engage the sole edge, and lateral arms engaging one of the plates to hold the loops in initial position, relative approach of the plates causing the loops to slip sidewise while maintaining the contact with the sole and separation of the plates allowing the

lateral arms to restore the loops to their initial position.

104. In a machine for applying pressure to shoe bottoms, an inflatable pad, a valve controlling the entrance of fluid to the pad and its exhaust therefrom, said valve being held by a spring in exhaust position, and means including a differential cylinder and piston for holding the valve in inflating position against said spring.

105. In a machine for applying pressure to shoe bottoms, a series of inflatable pads movable past an operating station, a valve controlling the entrance of fluid to each pad and its exhaust therefrom, each valve being held by a spring in exhaust position, and means including a differential cylinder and piston for holding each valve in inflating position against said spring.

106. In a machine for applying pressure to shoe bottoms, an inflatable pad, a valve controlling the entrance of fluid to the pad and its exhaust therefrom, said valve being held by a spring in exhaust position, means including a differential cylinder and piston for holding the valve in inflating position against said spring, and fluid-pressure-operated means for moving the valve to inflating position.

107. In a machine for applying pressure to shoe bottoms, a series of inflatable pads, a valve controlling the entrance of fluid to each pad and its exhaust therefrom, each valve being held by a spring in exhaust position, means including a differential cylinder and piston for holding each valve in inflating position against said spring, and a single means for opening the valves in turn.

108. In a machine for applying pressure to shoe bottoms, a series of inflatable pads movable past an operating station, a valve controlling the entrance of fluid to each pad and its exhaust therefrom, each valve being held by a spring in exhaust position, means including a differential cylinder and piston for holding each valve in inflating position against said spring, and fluid-pressure-operated means at the operating station for moving the valves in turn to inflating position.

109. In a machine for applying pressure to shoe bottoms, an inflatable pad, pressure-applying means comprising a cylinder and plunger, a valve controlling the entrance of fluid to the pad and its exhaust therefrom, said valve being biased to exhaust position, means including a differential cylinder and piston for holding the valve in inflating position, fluid-pressure-operated means for moving the valve to inflating position, and connections between said pressure-applying cylinder and said fluid-pressure-operated means which is opened when the plunger of the pressure-applying cylinder approaches the end of its stroke.

110. In a machine for applying pressure to shoe bottoms, an inflatable pad, pressure-applying means comprising a cylinder and plunger, a valve controlling the entrance of fluid to the pad and its exhaust therefrom, said valve being biased to exhaust position, means including a differential cylinder and piston for holding the valve in inflating position, fluid-pressure-operated means for moving the valve to inflating position, and a pipe connecting said pressure-applying cylinder to said fluid-pressure-operated means so that when the plunger of the pressure-applying cylinder has moved a part of its stroke the valve will be moved to inflating position.

111. In a machine for applying pressure to shoe bottoms, a series of inflatable pads movable past an operating station, means for applying

pressure to a shoe placed on the pad at the operating station, a valve controlling the entrance of fluid to each pad and its exhaust therefrom, each valve being held by a spring in exhaust position, means including a differential cylinder and piston for holding each valve in inflating position against said spring, fluid-pressure-operated means at the operating station for moving the valve to inflating position, and means dependent on application of pressure to the shoe for causing said fluid-pressure-operated means to operate.

112. In a machine for applying pressure to shoe bottoms, a series of inflatable pads movable past an operating station, pressure-applying means comprising a cylinder and plunger at the operating station, a valve controlling the entrance of fluid to each pad and its exhaust therefrom, each valve being biased to exhaust position, means including a differential cylinder and piston for holding the valve in inflating position, fluid-pressure-operated means at the operating station for moving each valve in turn to inflating position, and a passage between said pressure-applying cylinder and said fluid-pressure-operated means which is opened when the plunger of the pressure-applying cylinder has operated to apply pressure to the shoe whereby the valve of that pad is then opened to permit inflation of the pad.

113. In a machine for applying pressure to shoe bottoms, a pad to receive a shoe, fluid-pressure-operated means for applying pressure to the shoe, means for maintaining the pressure applied by said pressure-applying means, a valve biased to position permitting operation of the pressure-applying means, and means controlled by operation of said pressure-maintaining means to overcome the bias of said valve and cause exhaust of said pressure-applying means.

114. In a machine for applying pressure to shoe bottoms, a pad to receive a shoe, fluid-pressure-operated means for applying pressure to the shoe, means for maintaining the pressure so applied comprising a wedge biased to pressure-maintaining position, a second fluid-pressure-operated means for holding the wedge out of pressure-maintaining position, a valve biased to a position permitting operation of the pressure-applying means, a third fluid-pressure-operated means for overcoming said second fluid-pressure-operated means to permit operation of the wedge, and means controlled by operation of said third fluid-pressure-operated means to overcome the biasing of said valve and cause said pressure-applying means to be released.

115. In a machine for applying pressure to shoe bottoms, a pad to receive the shoe, a pair of bails, a first fluid-pressure-operated means for operating the bails to apply pressure to the shoe, a wedge for maintaining each bail in pressure-applying position, spring means urging said wedges to pressure-maintaining position, a valve biased to position to cause operation of said first fluid-pressure-operated means, a second fluid-pressure-operated means normally holding said wedges out of pressure-maintaining position, a third fluid-pressure-operated means for overcoming said second fluid-pressure-operated means to permit the spring means to act, and means controlled by operation of said third fluid-pressure-operated means to overcome the biasing of said valve and cause said first fluid-pressure-operated means to be exhausted.

116. In a cement sole-attaching machine, a turret, a series of inflatable pads carried by the

turret, means for holding the turret in indexed position, fluid-pressure-operated means for releasing the turret-holding means, fluid-pressure-operated means for inflating the pads, and a valve biased to closed position, the inflating pressure acting on said valve in opposition to said bias to open the valve and supply fluid to the turret-releasing means.

117. In a cement sole-attaching machine, a carrier rotatable about a vertical axis, a plurality of pads on the carrier to be presented in turn at an operating station by rotation of the carrier, and a set of gages for locating a sole, said gages being movable into and out of position over the pad at the operating station.

118. In a cement sole-attaching machine, a carrier rotatable about a vertical axis, a plurality of pads on the carrier to be presented in turn at an operating station by rotation of the carrier, and a single set of gages for locating the rear part of a sole and shoe arranged to move into and out of position over the pad at the operating station.

119. In a cement sole-attaching machine, a carrier rotatable about a vertical axis, a plurality of pads on the carrier to be presented in turn at an operating station by rotation of the carrier, the longitudinal axis of said pads being inclined at about forty-five degrees to the horizontal and located in planes extending radially of said axis, and a single set of gages for locating the forepart of the shoe and sole arranged for movement into and out of position over the pad at the operating station.

120. In a cement sole-attaching machine, a carrier rotatable about a vertical axis, a plurality of pads on the carrier to be presented in turn at an operating station by rotation of the carrier, the longitudinal axes of said pads being inclined at about forty-five degrees to the horizontal and lying in planes extending radially of the axis of the carrier, a single set of gages for locating the forepart of a shoe and sole movable into and out of position over the pad at the operating station, and a single set of gages for the rear part of the shoe and sole movable into and out of operative relation to each pad when it is at the operating station.

121. In a cement sole-attaching machine, a carrier rotatable about a vertical axis, a plurality of pads on the carrier to be presented at an operating station by rotation of the carrier, and a single set of gages for locating the rear part of a sole and shoe arranged to be moved at first heightwise of the pad and then into position over the pad at the operating station.

122. In a cement sole-attaching machine, a carrier rotatable about a vertical axis, a plurality of pads on the carrier to be presented in turn at an operating station by rotation of the carrier, said pads having rear parts adjustable heightwise, a set of gages for locating the rear part of a sole and shoe, a support carrying said gages arranged for movement to bring the gages into juxtaposition to the rear end of the pad, means operated by the support for moving the gages into operative position on the pad, and means for varying the movement of the support in accordance with the heightwise adjustment of the rear end of the pad.

123. In a cement sole-attaching machine, a carrier rotatable about a vertical axis, a plurality of pads on the carrier to be presented in turn at an operating station by rotation of the carrier, a support arranged for up-and-down move-

ment adjacent to the rear end of the pad at the operating station, gages for locating the rear part of a sole and shoe mounted on said carrier for movement about a horizontal axis, and means operated by upward movement of the support for swinging the gages about said axis into position on the pad.

124. In a cement sole-attaching machine, a carrier rotatable about a vertical axis, a plurality of pads on the carrier to be presented in turn at an operating station by rotation of the carrier, said pads being arranged with their longitudinal axes extending radially of the carrier at a downward and outward inclination with respect to said axis, and a set of gages for the forepart of the shoe arranged to be moved into and out of position over the forepart of the pad in a plane parallel to its sole-receiving surface.

125. In a cement sole-attaching machine, a carrier rotatable about a vertical axis, a plurality of pads on the carrier to be presented in turn at an operating station by rotation of the carrier, said pads being arranged with their longitudinal axes extending radially of the carrier at a downward and outward inclination with respect to said axis, a set of gages for the forepart of the shoe arranged to be moved into and out of position over the forepart of the pad in a plane parallel to its sole-receiving surface, and fluid-pressure-operated means for moving the gages into and out of operative position over the pad.

126. In a cement sole-attaching machine, a carrier rotatable about a vertical axis, a plurality of pads on the carrier to be presented in turn at an operating station by rotation of the carrier, said pads being arranged with their longitudinal axes extending radially of the carrier at a downward and outward inclination with respect to said axis, a set of gages for the forepart of the shoe arranged to be moved into and out of position over the forepart of the pad in a plane parallel to its sole-receiving surface, means for holding the gages out of position over the pad, and means operated by rotation of the carrier for releasing said holding means.

127. In a cement sole-attaching machine, a carrier rotatable about a vertical axis, a plurality of pads on the carrier to be presented in turn at an operating station by rotation of the carrier, said pads being arranged with their longitudinal axes extending radially of the carrier at a downward and outward inclination with respect to said axis, a set of gages for the forepart of the shoe arranged to be moved into and out of position over the forepart of the pad in a plane parallel to its sole-receiving surface, and manually controlled fluid-pressure-operated means for moving the gages into and out of operative position on the pad.

128. In a cement sole-attaching machine, a carrier rotatable about a vertical axis, a plurality of pads on the carrier to be presented in turn at an operating station by rotation of the carrier, a set of gages for locating the rear part of the shoe and sole arranged to be moved into and out of position over the rear part of the pad at the operating station, fluid-pressure-operated means for applying pressure to the shoe, fluid-pressure-operated means for causing the gages to approach each other, and means for separating the gages which is operated as an incident to the application of pressure to the shoe.

129. In a cement sole-attaching machine, a carrier rotatable about a vertical axis, a plurality

of inflatable pads on the carrier to be presented in turn at an operating station by rotation of the carrier, gages located at the operating station for relatively positioning the rear part of a shoe

5 and sole, a support for said gages arranged for up-and-down movement, means for raising the support to bring the gages into operative position on the pad, and means operated as an incident to the inflation of the pad for causing the support to be lowered.

130. In a cement sole-attaching machine, a carrier rotatable about a vertical axis, a plurality of pads on the carrier to be presented in turn at an operating station by rotation of the carrier,

15 fluid-pressure-operated means for applying pressure to a shoe and sole located on one of the pads, a set of forepart shoe and sole locating gages movable into and out of position over the pad at the operating station, manually operated means for initiating the operation of the fluid-pressure-operated means to apply pressure to the shoe, and fluid-pressure-operated means for removing the gages from operative position the action of which is initiated by operation of said

20 manually operated means.

131. In a cement sole-attaching machine, a carrier rotatable about a vertical axis, a plurality of pads on the carrier to be presented in turn at an operating station by rotation of the carrier,

30 fluid-pressure-operated means for applying pressure to a shoe and sole located on one of the pads, a set of forepart shoe and sole locating gages movable into and out of position over the pad at the operating station, manually operated means for initiating the operation of the fluid-pressure-operated means to apply pressure to the shoe, fluid-pressure-operated means for removing the gages from operative position the action of which is initiated by operation of said manually operated means.

40 132. In a cement sole-attaching machine, a carrier rotatable about a vertical axis, a plurality of pads on the carrier to be presented in turn at an operating station by rotation of the carrier, fluid-pressure-operated means for applying pressure to a shoe and sole located on one of the pads,

50 a set of forepart shoe and sole locating gages movable into and out of position over the pad at the operating station, manually operated means for initiating the operation of the fluid-pressure-operated means to apply pressure to the shoe, and fluid-pressure-operated means for moving the gages out of operating position the action of which is dependent upon operation of said manually operated means.

60 133. In a cement sole-attaching machine, a carrier rotatable about a vertical axis, a plurality of pads on the carrier to be presented in turn at an operating station by rotation of the carrier, fluid-pressure-operated means for applying pressure to a shoe and sole located on one of the pads,

65 a set of forepart shoe and sole locating gages movable into and out of position over the pad at the operating station, manually operated means for initiating the operation of the fluid-pressure-operated means to apply pressure to the shoe, and fluid-pressure-operated means for moving the gages into and out of operative position,

70 said gage-moving means being automatically actuated to remove the gages as a result of operation of said manually operated means and the

gages being returned to operative position as a result of movement of the carrier.

134. In a cement sole-attaching machine, a carrier rotatable about a vertical axis, a plurality of pads on the carrier to be presented in turn at an operating station by rotation of the carrier, fluid-pressure-operated means for applying pressure to a shoe and sole located on one of the pads, a set of forepart shoe and sole locating gages movable into and out of position over the pad at the operating station, a treadle for initiating the operation of said fluid-pressure-operated means to apply pressure to the shoe, fluid-pressure-operated means for removing the gages from operative position, a valve for controlling the operation of the gage-removing means, and means set in operation by depression of the treadle for operating said valve to cause removal of the gages. 10

135. In a cement sole-attaching machine, a carrier rotatable about a vertical axis, a plurality of pads on the carrier to be presented in turn at an operating station by rotation of the carrier, indexing means for holding the carrier against rotation, a first fluid-pressure-operated means for applying pressure to a shoe and sole located on one of the pads, a set of forepart shoe and sole locating gages movable into and out of position over the pad at the operating station, a second fluid-pressure-operated means for moving the gages out of operative position, and means for withdrawing said indexing means which can be operated only if the first fluid-pressure-operated means is in unoperated position and the second fluid-pressure-operated means is in operated position. 20

136. In a cement sole-attaching machine, a carrier rotatable about a vertical axis, a plurality of pads on the carrier to be presented in turn at an operating station by rotation of the carrier, means for turning the carrier, a gage support movable heightwise at the rear end of the pad at the operating station, an indexing pin for holding the carrier in indexed position, gages movable over the pad by upward movement of the support, means for withdrawing the pin, and means to prevent withdrawing the pin unless the gage support has descended. 30

137. In a cement sole-attaching machine, a carrier rotatable about a vertical axis, a plurality of pads on the carrier to be presented in turn at an operating station by rotation of the carrier, fluid-pressure-operated means for applying pressure to a shoe and sole located on one of the pads, a set of rear part shoe and sole locating gages movable into and out of position over the pad at the operating station, fluid-pressure-operated means for moving the gages toward each other to engage a sole, manually operated means for initiating operation of the fluid-pressure-operated means to apply pressure to the shoe, and fluid-pressure-operated means for separating the gages, said last-named means being operated as a result of applying pressure to the shoe. 40

138. In a cement sole-attaching machine, a carrier rotatable about a vertical axis, a plurality of inflatable pads on the carrier to be presented in turn at an operating station by rotation of the carrier, fluid-pressure-operated means for applying pressure to a shoe and sole located on one of the pads, means for inflating the pad, a set of heel-part shoe and sole locating gages movable into and out of position over the pad at the operating station, manually operated means for initiating inflation of the pad at the operating station, and gravity-actuated means for remov- 50

ing the gages from position over the pad which is permitted to operate only after the pad has been inflated.

139. In a cement sole-attaching machine, a carrier rotatable about a vertical axis, a plurality of pads on the carrier to be presented in turn at an operating station by rotation of the carrier, fluid-pressure-operated means for applying pressure to a shoe and sole located on one of the pads, a set of forepart shoe and sole locating gages movable into and out of position over the pad at the operating station, manually operated means for initiating the operation of the fluid-pressure-operated means to apply pressure to the shoe, fluid-pressure-operated means for removing the gages from operative position the action of which is initiated by operation of said manually operated means, means for locking the gages out of operative position, means operated by rotation of the carrier for releasing said locking means, and fluid-pressure-operated means acting automatically to return the gages to operative position upon release of said locking means. 60

140. In a machine for applying pressure to shoe bottoms, a turret, a pin for holding the turret in indexed position, a fluid-pressure-operated motor for turning the turret, a timing device, and means operated by the exhaust from said motor for setting the timing device to prevent operation of said pin until a predetermined time has elapsed. 70

141. In a cement sole-attaching machine, a carrier rotatable about a vertical axis, a plurality of pads on the carrier to be presented in turn at an operating station by rotation of the carrier, a fluid-pressure-operated rotary motor for turning the carrier, an indexing pin for holding the carrier in indexed position, fluid-pressure-operated means for withdrawing the pin, and a timing device set in operation by the exhaust from the fluid motor to prevent another withdrawal of said pin until a predetermined time has elapsed. 80

142. In a cement sole-attaching machine, a carrier rotatable about a vertical axis, a plurality of pads on the carrier to be presented in turn at an operating station by rotation of the carrier, gages movable into and out of position on the pads in turn for locating the soles on the pads, means for withdrawing the gages after each locating operation, a motor for rotating the carrier, an indexing pin for holding the carrier in indexed position, means for withdrawing the pin, means operated thereby for starting the motor, and means to prevent withdrawing the pin until the gages have been withdrawn from position on the pad. 90

143. In a cement sole-attaching machine, a carrier rotatable about a vertical axis, a plurality of pads on the carrier to be presented in turn at an operating station by rotation of the carrier, fluid-pressure-operated means for applying pressure to the shoe at the operating station, means for maintaining the pressure so obtained, a motor for turning the carrier, an indexing pin for holding the carrier in indexed position, means for withdrawing the pin, and means to prevent operation of said pin-withdrawing means unless the pressure-applying means has ceased to operate. 100

144. In a cement sole-attaching machine, a carrier rotatable about a vertical axis, a plurality of pads on the carrier to be presented in turn at an operating station by rotation of the carrier, gages movable into and out of position over the pad at the operating station, a motor for turning

the carrier, means holding the carrier in indexed position, and means to prevent release of the carrier-holding means unless the gages are withdrawn from over the pad.

145. In a cement sole-attaching machine, a carrier rotatable about a vertical axis, a plurality of pads on the carrier to be presented in turn at an operating station by rotation of the carrier, means for applying pressure to a shoe on the pad at the operating station, a motor for turning the carrier, means for holding the carrier in indexed position, and means to prevent release of the carrier-holding means unless the pressure-applying means has ceased to act on the shoe.

146. In a cement sole-attaching machine, a carrier rotatable about a vertical axis, a plurality of pads on the carrier to be presented in turn at an operating station by rotation of the carrier, indexing means for holding the carrier against rotation, fluid-pressure-operated means for applying pressure to a shoe and sole located on one of the pads, a set of forepart shoe and sole locating gages movable into and out of position over the pad at the operating station, fluid-pressure-operated means for moving the gages out of operative position, and fluid-pressure-operated means for withdrawing said indexing means, the supply of fluid to said withdrawing means being dependent on the return of the fluid-pressure-operated pressure-applying means to initial position and on operation of the fluid-pressure-operated means to remove the gages from operative position.

147. In a cement sole-attaching machine, a carrier rotatable about a vertical axis, a plurality of pads on the carrier to be presented in turn at an operating station by rotation of the carrier, a fluid-pressure-operated rotary motor for turning the carrier the exhaust of which is closed to prevent its operation, an indexing pin for holding the carrier in indexed position, means for withdrawing the pin, means operated by withdrawal of the indexing pin for opening the exhaust of the rotary motor, a spring-pressed piston in a cylinder which in the position due to action of the spring permits said indexing-pin-withdrawing means to be operated and when moved in opposition to said spring prevents such operation, and connections from the exhaust of the rotary motor for moving said piston in the direction opposed by the spring.

148. In a cement sole-attaching machine, a carrier rotatable about a vertical axis, a plurality of pads on the carrier to be presented in turn at an operating station by rotation of the carrier, a fluid-pressure-operated motor for turning the carrier, means for closing the exhaust of the motor, means for holding the carrier in indexed position, fluid-pressure-operated means for releasing the carrier-holding means, means operated by release of the carrier-holding means for opening the exhaust of the motor, and means operated by said exhaust for preventing operation of said fluid-pressure-operated means for releasing the carrier until a predetermined period of time has elapsed.

149. In a cement sole-attaching machine, a carrier rotatable about a vertical axis, a plurality of pads on the carrier to be presented in turn at an operating station by rotation of the carrier, a fluid-pressure-operated motor for turning the carrier, means for closing the exhaust of said motor, an indexing pin for holding the carrier in indexed position, fluid-pressure-operated means for withdrawing the pin, means operated

by withdrawal of the indexing pin for opening the exhaust of the motor, and means operated by said exhaust for preventing operation of the indexing-pin-withdrawing means for a predetermined time.

150. In a machine for applying pressure to shoe bottoms, a turret, a fluid-pressure-operated motor for rotating the turret, an indexing pin for holding the turret from rotation, fluid-pressure-operated means for withdrawing the indexing pin, means operated by the withdrawal of the indexing pin for opening the exhaust of the motor, a spring-operated piston in a cylinder which in one position permits passage of fluid to said indexing-pin-withdrawing means and when moved against said spring cuts off such passage, connections from the exhaust of the rotary motor for moving said piston, and a needle valve for timing the return movement of the piston to open said passage.

151. In a cement sole-attaching machine, a carrier rotatable about a vertical axis, a plurality of pads on the carrier to be presented in turn at an operating station by rotation of the carrier, a fluid-pressure-operated rotary motor for turning the carrier the exhaust of which is closed to prevent its operation, an indexing pin for holding the carrier in indexed position, fluid-pressure-operated means for withdrawing the pin, means operated by withdrawal of the indexing pin for opening the exhaust of the rotary motor, a spring-pressed piston in a cylinder which in the position due to action of the spring permits passage of fluid to said indexing-pin-withdrawing means and when moved against said spring prevents such passage, connections from the exhaust of the rotary motor for moving said piston in the direction opposed by the spring, and a needle valve for controlling the exhaust of fluid from said cylinder in response to reaction of said spring.

152. In a cement sole-attaching machine, a carrier rotatable about a vertical axis, a plurality of pads on the carrier to be presented in turn at an operating station by rotation of the carrier, a fluid-pressure-operated motor for turning the carrier, means for closing the exhaust of said motor, an indexing pin for holding the carrier in indexed position, fluid-pressure-operated means for withdrawing the pin, means operated by withdrawal of the indexing pin for opening the exhaust of the motor, and timing means set in operation by starting of the motor for preventing a second withdrawal of the pin until a predetermined time has elapsed.

153. In a cement sole-attaching machine, a carrier rotatable about a vertical axis, a plurality of pads on the carrier to be presented in turn at an operating station by rotation of the carrier, a fluid-pressure-operated motor for turning the carrier, the exhaust of the motor being normally closed to prevent operation of the motor, an indexing pin for holding the carrier in indexed position, fluid-pressure-operated means for withdrawing the pin, means operated by withdrawal of the indexing pin for opening the exhaust of the rotary motor, a cylinder and a spring-pressed piston therein which, when the spring is expanded, permits passage of fluid to said indexing-pin-withdrawing means and, when moved against said spring, prevents withdrawal of the pin, said cylinder having a port which is open when the piston is moved against said spring to permit continued operation of the motor, and

connections from the exhaust of the rotary motor for moving said piston to open said port.

154. In a cement sole-attaching machine, a carrier rotatable about a vertical axis, a plurality of pads on the carrier to be presented in turn at an operating station by rotation of the carrier, a fluid-pressure-operated motor for turning the carrier, the exhaust of the motor being normally closed to prevent operation of the motor, an indexing pin for holding the carrier in indexed position, fluid-pressure-operated means for withdrawing the pin, means operated by withdrawal of the indexing pin for opening the exhaust of the rotary motor, a cylinder and a spring-pressed piston therein which, when the spring is expanded, permits passage of fluid to said indexing-pin-withdrawing means and, when moved against said spring, prevents withdrawal of the pin, said cylinder having a port which is open when the piston is moved to the limit against said spring to permit continued operation of the motor, and means permitting slow leakage of fluid from said cylinder to allow return of the piston to initial position under the influence of the spring whereupon withdrawal of the pin is permitted.

155. In a cement sole-attaching machine, means for applying pressure to the shoe, a device for determining the length of time the shoe is held under pressure comprising a cylinder, a piston in said cylinder, a spring for moving the piston in one direction, a source of fluid pressure for moving the piston against said spring, means for cutting off the supply of pressure fluid to said cylinder when pressure is being applied to the shoe, means permitting slow discharge of fluid from said cylinder under influence of said spring, and means controlled by movement of said piston for determining the time during which the shoe is held under pressure.

156. In a cement sole-attaching machine, a carrier rotatable about a vertical axis, an inflatable pad on the carrier, a fluid-pressure-operated clamping mechanism on the carrier for pressing a shoe on the pad, means for supplying fluid under pressure to operate said mechanism, and means controlled by the operation of said mechanism for causing inflation of the pad.

157. In a cement sole-attaching machine, an intermittently rotatable carrier, an inflatable pad on the carrier, a fluid-pressure-operated clamping mechanism on the carrier for pressing a shoe on the pad, means for supplying fluid under pressure to operate said mechanism and to inflate said pad, and automatic means for sequentially exhausting said pad and raising said clamping mechanism to permit removal of the shoe.

158. In a cement sole-attaching machine, a movable carrier, a plurality of inflatable pads on the carrier, means for advancing the carrier step by step to present the pads in turn at an operating station, fluid-pressure-operated means for applying pressure to a shoe on one of the pads, means for inflating the pad, and means operable only after the pad is deflated for relieving the pressure on the shoe.

159. In a cement sole-attaching machine, the combination of a rotatable carrier, a plurality of inflatable pads on the carrier, fluid-pressure-operated means for pressing a shoe on one of the pads, a valve for controlling the supply of fluid to said fluid-pressure-operated means, a valve for controlling admission of fluid to said pad, and means for preventing inflation of the pad unless pressure has been applied to the shoe.

160. In a cement sole-attaching machine, a ro-

tary carrier, inflatable pads on the carrier, fluid-pressure-operated means for pressing a shoe on one of the pads, a first valve for controlling the supply of fluid to said means, a second valve for controlling admission of fluid to said pad, and means insuring that operation of the second valve will not be effected to inflate the pad unless the first valve has been operated.

161. In a cement sole-attaching machine, a rotary carrier, inflatable pads on the carrier, fluid-pressure-operated means for pressing a shoe on one of the pads, a first valve for controlling the supply of fluid to said means, a second valve controlling admission of fluid to said pad, and means preventing operation of the second valve from being effective to inflate the pad unless the first valve has been operated.

162. In a cement sole-attaching machine, a rotatable carrier, a plurality of pads on the carrier, means for rotating the carrier to present the pads in turn at an operating station, fluid-pressure-operated means for pressing a shoe on the pad at the operating station, means for maintaining the pressure on the shoe after the fluid-pressure-operated means has ceased to act, and means to prevent release of said pressure until the pad is again presented at the operating station by rotation of the carrier.

163. In a cement sole-attaching machine, a rotary carrier, pads on the carrier, gages operable for locating a shoe and its sole on one of the pads while the carrier is at rest, means for rotating the carrier, and means preventing operation of the gages during rotation of the carrier.

164. In a cement sole-attaching machine, the combination of a rotary carrier, a series of inflatable pads on the carrier, and a timing device controlled by inflation of a pad on the carrier, said device determining the time which must elapse before a pad may be deflated.

165. In a shoe machine, work-receiving means, pressure-applying means arranged to operate on a work-piece on the work-receiving means, said pressure-applying means comprising a member movable toward and away from the work-receiving means, and a work-engaging member slidable on said movable member laterally of the work so that it can be moved out of the way when not in use.

166. In a cement sole-attaching machine, work-receiving means, a bail arranged to apply pressure to a work-piece on the work-receiving means, an abutment slidably mounted on the bail for movement to an out-of-the-way position when not in use, and a member adapted to swing the bail over the work-piece and to move the work-engaging member into alignment with the work-piece on the receiving means.

167. In a shoe machine, a pressure-applying member having a last-engaging surface, and a finger associated with said surface and arranged to position said surface in a predetermined manner on the last.

168. In a shoe machine, a pressure-applying member having a last-engaging surface, and a finger associated with the last-engaging surface and arranged for engagement with the last for positioning the work-engaging surface on the last.

169. Gage mechanism for use in shoe machines comprising a pair of gages each having a sole-engaging portion and a shoe-engaging portion, said shoe-engaging portions being inclined heightwise with respect to the sole-engaging por-

tion to guide a shoe into proper relation to a sole positioned by said sole-engaging portions.

170. In a cement sole-attaching machine, a pad, gages at the rear end of the pad for locating a sole centrally thereof, and shoe gages associated with the sole gages and having inclined surfaces acting to direct a shoe placed on the sole downwardly into the proper relation to the sole located by the sole gages.

171. In a cement sole-attaching machine, a pad, gages at the rear end of the pad for locating a sole centrally thereof, shoe gages associated with the sole gages and having downwardly and inwardly inclined surfaces acting to direct a shoe placed on the sole into the proper relation to the sole located by the sole gages, and means for adjusting the shoe gages laterally of the sole with respect to the sole gages.

172. In a cement sole-attaching machine, a pad, gages at the rear end of the pad for locating a sole centrally thereof, shoe gages associated with the sole gages and having downwardly and inwardly inclined surfaces acting to direct a shoe placed on the sole into the proper relation to the sole located by the sole gages, and means for adjusting each shoe gage laterally of the sole with respect to the associated sole gage.

173. In a cement sole-attaching machine, a pad to receive a sole, gages for locating the sole at the ball line, gages for locating the sole at the breast line, means for operating the gages to locate the sole with the longitudinal median line of the rear part parallel to the longitudinal axis of the pad, a sole toe gage for engaging the toe of the sole, means carried by the sole toe gage for locating the toe end of a shoe, and shoe gages associated with the breast-line gages and having downwardly and inwardly inclined surfaces for engaging the shoe adjacent to the breast line for directing the shoe into a central position with respect to the rear part of the sole.

174. In a cement sole-attaching machine, a carrier rotatable about a vertical axis, inflatable pads on the carrier to be presented in turn at an operating station by rotation of the carrier, clamping mechanism on the carrier for clamping a shoe on each pad, means at the operating station for operating the clamping mechanism, and means controlled by operation of said means for causing inflation of the corresponding pad.

175. In a cement sole-attaching machine, a pad to receive a sole, gages for locating the sole at the ball line, gages for locating the sole at the breast line, means for operating the gages, a sole toe gage for engaging the toe of the sole, means carried by the sole toe gage for locating the toe end of the shoe, and shoe gages associated with the breast-line gages and having downwardly and inwardly inclined surfaces for engaging the shoe adjacent to the breast line for directing the shoe into a central position with respect to the rear part of the sole.

176. In a machine for applying pressure to shoe bottoms, a pad, means for applying pressure to a shoe to press it upon the pad comprising a bail arranged to swing longitudinally of the shoe, a toe abutment carried by the bail, a stop for arresting movement of the bail, and means for automatically setting the stop in accordance with the length of the shoe.

177. In a machine for applying pressure to shoe bottoms, an inflatable pad, a mask plate on the pad for controlling the distortion of the pad, said mask plate being movable longitudinally of the pad, a toe gage, and connections between the toe

gage and the mask plate to cause the mask plate to be positioned in accordance with the position assumed by the toe gage.

178. In a machine for applying pressure to shoe bottoms, an inflatable pad, a mask plate on the pad for controlling the distortion of the pad, said mask plate being movable longitudinally of the pad in the direction of the longitudinal median line of the forepart of a sole placed on the pad, 10 a toe gage for engaging the sole placed on the pad, and connections between the toe gage and said mask plate to cause the mask plate to be positioned in accordance with the length of a sole located on the pad by the toe gage.

179. In a machine for applying pressure to shoe bottoms, a yielding pad, a mask plate on the pad for controlling the distortion of the pad, said mask plate being movable longitudinally of the pad, a spring normally holding the mask plate in retracted position, a toe gage movable longitudinally of the pad to engage a sole thereon, and means to engage the mask plate and move it toward the rear end of the pad to an extent determined by the position of said toe gage.

180. In a machine for applying pressure to shoe bottoms, a pad, means for applying pressure to a shoe to press it on the pad comprising an abutment movable longitudinally of the shoe to locate it with respect to the forepart thereof, a toothed 20 bar movable longitudinally of the pad, means for moving the bar a distance proportional to the length of the shoe, a pawl for locking the bar from rearward movement, said pawl being held out of engagement with the bar by the abutment when 30 in its forward position, means positioned by movement of the bar for arresting movement of the abutment, and means for causing the pawl to engage the teeth of the bar upon initial movement of the abutment.

181. In a machine for applying pressure to shoe bottoms, a pad, means for applying pressure to a shoe to press it on the pad comprising a bail arranged to move longitudinally of a shoe on the pad, a toe rest carried by the bail, a bar movable 40 longitudinally of the pad, means for locking the bar against movement, the locking means being rendered inoperative by the bail when in its normal forward position and rendered operative by movement of the bail over the shoe, and a stop 50 located upon movement of the bar to arrest rearward movement of the bail in accordance with the length of the shoe.

Certificate of Correction

Patent No. 2,445,848.

July 27, 1948.

SIDNEY J. FINN

It is hereby certified that errors appear in the printed specification of the above numbered patent requiring correction as follows:

Column 36, lines 16 and 17, for "motors" read *motor*; lines 17 and 18, strike out "and by the line 1264 to the motors" and insert the same after "M-12," in line 17, same column 36; column 37, line 21, for "pin 1400" read *pin 1986*; line 22, for "line 1368" read *line 1400*; column 48, line 40, claim 83, for "bare" read *bars*; and that the said Letters Patent should be read with these corrections therein that the same may conform to the record of the case in the Patent Office.

Signed and sealed this 26th day of April, A. D. 1949.
